SIGNALING SYSTEM

John E. Ostline, Chicago, Ill., assignor to Associated Electric Laboratories, Inc., Chicago, Ill., a corporation of Delaware

Application October 13, 1937, Serial No. 168,726

43 Claims. (Cl. 179—18)

The present invention relates to signaling systems and more particularly to switching apparatus for use in automatic telephone systems.

In an automatic telephone system of any considerable size, a large number of switching units are necessary for performing the various line-selecting functions required in establishing desired connections between the many lines of the system. Several types of switching units for performing the above-noted functions are known in the art. One improved form of unit, which is well adapted for use in the application noted and which possesses distinct advantages with respect to its features of construction and mode of operation, is disclosed and claimed in the present applicant's co-pending application Serial No. 147,810, filed June 12, 1937. Briefly described, this unit comprises a circuit control element having mounted thereon contact segments rotatable with the control element in either of two directions to make or break contact between a multiplicity of wipers or bank conductors. These bank conductors are arranged in two sets so that, when the control element associated therewith is moved or rotated in one direction, the conductors or wipers of one set are connected to the respective associated contact segments, whereas, if the control element is moved or rotated in the reverse direction, the conductors or wipers of the other set are connected to the contact segments. The arrangement as disclosed in the above-referred to copending application is such that the control elements of the various units are susceptible of being actuated by an operating member common to a group of the units and movable in either of two directions to actuate any controlling element operatively associated therewith in one or the other of its two directions of movement. Normally, the control elements are non-operatively associated with the operating member common thereto, means including clutch magnets individually included in the units being provided for operatively associating the respective elements with the operating member to be actuated thereby. The operating member is in turn arranged to be moved in either of two directions by means comprising a pair of operating magnets. When one of these two operating magnets is energized, the operating member is actuated to move any control element operatively associated therewith in a direction to cause engagement between the contact segments carried thereby and one set of associated bank conductors. With the other magnet energized any control element opera-

tively associated with the operating member is rotated in the reverse direction to bring the contact segments carried thereby into engagement with the other set of bank conductors. The form of switching unit noted, together with the apparatus common to a group thereof for selectively operating the units of the group, is of exceedingly small size, is economical to manufacture and install, and is entirely reliable in operation.

It is an object of the present invention to provide a signaling system, and more particularly an automatic telephone system, embodying switching units of the above form and wherein the control apparatus consists primarily of standard rotary switches and relays arranged in a simple manner such that a minimum amount of apparatus is required for a system of a given size.

It is a further object of the invention to provide, in a system of the character described, an improved line-selecting switch having a novel mode of operation such that the amount of apparatus required for a switch of a given size is reduced to a minimum.

It is another and more specific object of the invention to provide, in an automatic telephone system, an improved finder switch comprising switching units of the form just described so connected and arranged that the switch automatically operates to find, in an exceedingly short time interval, a calling line included in a group of lines extending thereto.

It is a still further object of the invention to provide, in an automatic telephone system, an improved impulse responsive line-selecting switch having embodied therein switching units of the form briefly described above.

In general, the objects as set forth above are attained in accordance with the present invention by providing, in a system of the character noted, a plurality of improved finder-connector links for inter-connecting the lines of the system for communication thereover, and allotting means of improved arrangement for assigning the links to successively calling lines in a definite order. It will be understood that, when the apparatus is used in an automatic telephone system having a plurality of lines, at least a portion of the lines will have individually associated therewith subscribers' substations, each including an impulsing device of conventional form. The lines of the system are divided into odd and even numbered groups, and included in each finder switch is means responsive to the initiation of a call.

on any one of the lines terminating at the switch for selecting an odd numbered group of lines and an even numbered group of lines, one of which includes the calling line. Each finder switch also includes means for further selecting the one of the two selected groups of lines which includes the calling line and for simultaneously selecting a sub-group of lines in the selected group of lines, which sub-group includes the calling line. The units selection of the calling line is accomplished through the provision of means comprising a rotary stepping switch of standard construction for selecting the calling line from the selected sub-group of lines, which means also operates to condition the connector portion of the associated link to be responsive to impulses transmitted from the impulsive device included in the substation associated with the calling line. In the connector switch, forming a part of each finder-connector link, there is provided means responsive to one series of impulses transmitted from the impulsive device at the calling substation for selecting a group of lines which includes a called line. Thereafter, means comprising a rotary stepping switch are caused to operate in response to a second series of impulses transmitted from the impulsive device at the calling substation to select a sub-group of lines in the selected group of lines and including the called line. Finally, means comprising another rotary switch are caused to operate to select the desired line from the selected sub-group of lines.

More specifically, each of the finder and connector switches comprises a plurality of switching units of the form just described, each of which has terminating therewith a number of the lines of the system, the line-terminating arrangement being such that when the control element of any unit is moved or rotated in one of its two directions of movement the unit selects a sub-group of lines included in an odd numbered group of lines, whereas movement of the control element in its other direction of movement results in the selection of a sub-group of lines included in an even numbered group of lines. In the case of a finder switch, the means which responds to the initiation of a call on a calling line, selects a group of the switching units having extending thereto an odd numbered group of lines and an even numbered group of lines one of which includes the calling line. Thereafter, the line sub-group selecting means operates to select from the selected group of units the unit to which the calling line extends and to determine, in accordance with the odd or even number identifying the group of lines including the calling line, the direction of movement of the control element embodied in the selected unit. Following the operation of the sub-group selecting means the control element of the selected unit is moved to connect the lines of the selected sub-group, which includes the calling line, to the bank contacts of the rotary stepping switch, referred to above, and provided for selecting the calling line from the selected sub-group of lines.

Each of the line group and line sub-group selecting means, as well as the line units selecting means, comprises a rotary stepping switch of standard construction which conventionally comprises a motor magnet for driving the wipers respectively associated with the various sets of bank contacts embodied therein. These motor magnets are connected and arranged successively

to interact with a relay thereby successively to drive their respective associated wipers. When energized and operatively associated with any one of the motor magnets, this relay includes contacts interrupting the operating circuit of the associated magnet, and, similarly, any one of the motor magnets, when energized and operatively associated with the relay noted, includes contacts interrupting the operating circuit of the relay. This feature of the invention is designed to reduce the cost of each link by reducing the number of control relays embodied therein.

By virtue of the above described novel method of line selection, each finder switch is rendered exceedingly fast in its operation to find and seize a calling line, all without excessive operating speeds on the part of the various rotary switches involved. In this connection, it is mentioned here that in a finder switch of the specific form described hereinafter, designed to have access to one thousand lines, the line group selecting function is completely performed at the end of a maximum of five steps taken by the rotary stepping switch provided for performing the line group selection. Similarly, the line sub-group selection is completed when the rotary stepping switch provided for this purpose has taken a maximum of five steps. Further in accordance with this feature of reducing the line-hunting time interval, the line units selecting switch is arranged so that in operation it tests the lines of a selected sub-group of lines in pairs. To this end, each sub-group of lines, as extended to the bank contacts of the last-mentioned rotary switch, are broken down into two smaller sub-groups; the lines of which terminate at different sets of the bank contacts. A pair of relays, one of which corresponds to one of the small sub-groups of lines and the other of which corresponds to the other small sub-groups of lines, are provided for performing line-testing functions. By this specific arrangement the lines of a sub-group of twenty lines may all be tested by ten steps on the part of the rotary switch. Thus, a combined maximum of twenty steps on the part of the three stepping switches suffices to cause any line of a thousand line plurality to be searched for and selected by any finder switch.

The connector or line-selecting switches are somewhat similar to the finder switches in that each thereof comprises a plurality of switching units having a number of the lines of the system terminating therewith, and the control element of each unit is movable in one direction to select a sub-group of lines included in an odd numbered group of lines and in another direction to select a sub-group of lines included in an even numbered group of lines. The first impulse responsive means, as referred to above, functions to select a group of switching units to which extend an odd numbered group of lines and an even numbered group of lines, one of which includes the desired or called line, and, also, to determine the direction of movement of the control elements respectively embodied in the units of the selected group in accordance with the odd or even number identifying the group of lines which includes the desired line. The means referred to above, which responds to the second series of received impulses, normally functions to select, from the selected group of units, the unit at which the desired line terminates, the control element of this unit being subsequently moved in the direction determined by the oper-

ation of the selecting means which responds to the first series of received impulses. The last-mentioned operation serves to connect the sub-group of lines including the called line to the bank contacts of the rotary switch, mentioned above, which functions to select the desired line from the selected sub-group of lines. In the particular arrangement disclosed, each sub-group comprises twenty lines and in order to adapt this number of lines to the decimal system of selection, conventionally employed, there is provided a wiper switching relay for selectively associating the link line extending to the connector switch with either of two smaller sub-groups, of ten lines each, making up a sub-group of lines extended by way of one of the switching units to the bank contacts of the rotary switch noted. This relay is under the control of the means which responds to the second series of received impulses and the condition thereof is determined by the number of impulses comprising the second series of impulses transmitted from a calling subscriber's substation.

Each of the finder-connector links also includes means for testing a selected called line to determine its idle or busy condition, means for establishing a connection between the calling and called lines in the event the called line is idle, and means for applying busy tone current to the calling line in the event the called line is found busy. Further features of the invention relate to the specific circuit arrangements whereby the elements of the various means briefly referred to above perform the particular functions assigned thereto.

In accordance with a further feature of the invention means comprising the impulse responsive means described above are provided for causing the switching units embodied in each connector switch automatically to select an idle trunk line from a small group of such lines upon the dialing of a predetermined two digit number at a calling subscriber's substation. As pointed out more particularly hereinafter, this means operates in a manner such that a clear metallic circuit is established through a seized link following the seizure thereby of one of the trunk lines.

The novel features believed to be characteristic of the invention are set forth with particularity in the appended claims. The invention itself, however, both as to its organization and method of operation, together with further objects and advantages thereof, will best be understood by reference to the specification taken in connection with the accompanying drawings, in which Figure 1 illustrates switching apparatus constructed and arranged in accordance with the invention disclosed in the above referred to co-pending application; Fig. 2 is a broken side view showing the details of one of the switching units shown in Fig. 1; Fig. 3 is a view, partially in section, taken along the lines 3-3 of Fig. 2; Fig. 4 is a view illustrating the details of the clutching mechanism incorporated in the switching unit shown in Figs. 1 and 2; Figs. 5 and 6 illustrate the finder portion of a finder-connector link embodied in an automatic telephone system constructed and arranged in accordance with the present invention; Fig. 7 illustrates the allotter means embodied in the system; and Figs. 8, 9 and 10 illustrate the connector portion of the finder-connector link including the finder switch shown in Figs. 5 and 6.

Referring now more particularly to Fig. 1 of the drawings, there is illustrated the improved

switching apparatus disclosed and claimed in the above-referred to co-pending application. In brief the apparatus comprises a frame 10, divided into two sections 11 and 12 for respectively accommodating a plurality of switching units 13, 14, 15, etc., and means common to these units for actuating the various circuit controlling elements thereof. The three units 13, 14 and 15 are shown as being mounted on the frame 10 within the section 11 by means comprising bolts 16 and 17 extending through the top and bottom members 8 and 9, respectively, of the frame 10. It is contemplated that with this arrangement the size of the section 11 for a frame 10 designed to accommodate the switching units for a particular installation shall be sufficient to accommodate the number of units ultimately required to serve the maximum estimated line capacity of the apparatus.

The actuating means for the various circuit controlling elements embodied in the several switching units comprises a member 18, slidably mounted in openings provided in the end and intermediate members 19, 20 and 21 of the frame 10 and having rigidly supported thereon a magnetic piece 22, which forms the armature for each of two actuating magnets 23 and 24 mounted respectively on the frame members 20 and 21 by means of screws 25 and 26. The actuating member 18 is restrained in a normal position when both of the two magnets 23 and 24 are deenergized by means comprising coil springs 27 and 28 cooperating respectively with pivoted arms 29 and 30 which bear against opposite sides of the armature piece 22. The arm 29 is pivotally mounted on the upper member of the frame 10 and is limited in its movement to the left through the force exerted thereon by the spring 27 by a stop pin 31 also mounted on the frame 10 in any suitable manner. Similarly, the arm 30 is pivotally mounted on an extension 32 of the member 21 and is limited in its movement to the right under the force of the spring 28 by a stop pin 33 also supported on the frame 10. It will be observed that the member 18 is movable in either of two directions depending upon which of the two magnets 23 and 24 is energized. Thus, if the magnet 23 is energized, it attracts the armature piece 22 to the left against the bias of the spring 28 to move the armature piece to the left. In a similar manner and with the member 18 and the armature piece 22 in the position shown, when the magnet 24 is energized, these two members are moved to the right against the force exerted thereon by the spring 27. It is noted that the frame 10, the member 18 and the armature 22 are all constructed of magnetic material, such, for example, as iron, thereby to provide a low reluctance, substantially closed, magnetic circuit for the flux produced when either of the two magnets is energized and to enhance the force exerted on the armature piece 22 following energization of either of the two magnets.

Referring now more particularly to Figs. 2, 3 and 4 of the drawings, wherein the switching unit indicated generally at 13 is shown in greater detail, this unit comprises a frame 34 having right angularly bent end portions 35 and 36, between which the circuit controlling element comprising a shaft 37 is rotatably mounted. At its left end, 70 this shaft is supported by a bronze bearing cap 38, threaded into the end portion 36 and drilled to provide a bearing surface for the shaft. At its right end, the shaft 37 is supported in a bearing surface formed by drilling the end portion 35 75

of the frame 34. Supported on and insulated from the shaft 37 by means comprising an insulating tube 39 are a plurality of contact segments 40 alternated with a plurality of insulating washers 41. For the purpose of fixedly positioning the segments 40 on the shaft 37, there is provided a fiber key 42 which is adapted to rest in a key slot formed in the shaft and to extend through suitably formed keyways cut in the tube 39, the segments 40 and the washers 41. The segments 40 and the insulating washers 41 are pressed together against an annular ring 43 by means comprising a nut 44 threaded on the right extremity of the shaft. It will be noted that the ring 43 is fixedly mounted on the shaft 37 by a pin 45 driven into a tapered drill hole extending through the ring and the shaft.

Each of the contact segments 40 is electrically connected to a terminal 46 by a flexible pigtail connector 47, formed of copper braid or the like, soldered at its ends to the associated segment and terminal. As best shown in Fig. 3, the various terminals 46 are clamped between two members 48 and 49 constructed of insulating material by screws 50 extending through the two members noted and threaded into tapped drill holes provided in the frame 34. These terminals are adapted to be connected to the conductors forming the lines incoming to the switching unit. By this arrangement, a switching unit of extremely small size for a given line capacity is obtained.

As shown more particularly in Figs. 2 and 3, each of the contact segments 40 is roughly triangular in shape, is rounded at its upper end, and is provided with a V-shaped groove, the sides of which form the contacting surfaces for engaging with either of two associated wipers. These wipers form two sets comprising respectively the resilient conductors 51 and 52 arranged in rows with their ends disposed on opposite sides of the contact segments. Preferably, these conductors are constructed of bronze or like resilient material and are supported on the frame 34 by clamping the same at the upper ends thereof between insulating members 53, 54 and 55. The members noted are clamped together and to the frame 34 by screws 56 extending therethrough and threaded into tapped drill holes provided in the frame 34. For the purpose of guiding the various wipers in their movement, there is provided intermediate the upper and lower ends thereof a guide member 57 of insulating material supported on the frame 34 by means comprising spacing members 58, located at each end of the member 57, and clamping screws 60. Each of the wipers 51 and 52 is tensioned or biased into engagement with this member and moves in a guide slot provided therein when engaged by its respective associated contact segment 40. The lower ends of the wipers 51 and 52 are curved outward to insure a smooth engagement with the respective associated contact segments when the segments are rotated into engagement therewith. It will be observed that the V-shaped groove provided in the engaging end of each of the segments insures a two-point contact between the segment and its associated wipers. It will be observed further that during rotation of the segments a slidably engagement occurs between each segment and its respective associated wipers to provide a self-cleaning action of the contacting surfaces. Normally, the segments are restrained in the position shown in Fig. 3 of the drawings by means comprising a coil spring 61 connected between an arm 62 projecting from the annular

ring 43 and an eye 63 clamped between the insulating members 48 and 49. From this normal position, the shaft 37 is adapted to be rotated about its axis in either a clockwise or counter-clockwise direction, thereby to bring the commutating segments 40 into engagement with the respective associated wipers 51 or 52 of the two wiper sets. Such rotation of the shaft 37 is accomplished through operation of the actuating member 18 from the normal position shown in Fig. 1 to one or the other of its two off-normal positions. To this end, and as best shown in Figs. 2 and 4, the member 18 is provided with a clutch projection 64 extending from the edge thereof, which projection is adapted to cooperate with a clutching element 65, slidable axially along the shaft 37, and normally restrained to the left out of engagement with the projection 64 by a coil spring 67, interposed between the clutching element and the annular ring 43 and enclosing the shaft 37. A pin 66, extending through a drill hole provided in the shaft, engages the sides of a slot 68 cut in the shank portion 69 of the clutch element 65 to form a stop against which the element 65 is normally braced, to guide the element 65 in its movement axially along the shaft 37 and to provide means for mechanically coupling the element 65 with the shaft 37. The radially extending flange portion of the element 65 has formed at its lower end two fingers 70 and 71 within which the projection 64 on the member 18 is adapted to extend when the element 65 is moved to the right. It will be noted that the sides of the fingers 70 and 71 for engaging the projection 64 are rounded so that, when the member 18 is moved in either of its directions of movement, free and unrestricted movement of the element 65 to rotate the shaft 37 is obtained.

For the purpose of moving the clutching element 65 to the right to a position such that the projection 64 on the actuating member 18 extends between the fingers 70 and 71, there is provided a small relay or clutch magnet 72 mounted on an inturned portion 59 of the frame side member 36 by means of a screw 74. Pivotedly mounted at 75 in a slot formed in the member 36 is an armature 76 having mounted thereon an arm 77. This arm 77 is slotted at its lower end to form two fingers 79 and 80 which extend over the shaft 37 and are adapted to engage the left end of the shank 69 forming a part of the clutching element 65. The frame 34, and more particularly the side member 36 thereof, is formed of magnetic material, such, for example, as iron, whereby a substantially closed magnetic circuit, including the armature 36, is provided for the flux produced when the magnet 72 is energized. For purposes of control, there is mounted on the frame side member 36 a contact spring assembly 81, comprising two or more contact springs clamped between insulating members as shown, and secured to the frame member 36 by a screw 82. The making and breaking of contact between the two springs comprising the assembly 81 is under the control of an arm 82 formed integrally with the armature 76 and provided with an insulating cap 83 for engaging the lower end of the right hand spring included in the spring assembly. In order to hold the shaft 37 and the segments carried thereby operated independently of the condition of the magnet 72 and following the energization of this magnet and one or the other of the magnets 23 and 24, the projection 64 is preferably made of square or triangular cross section and the inner opposite sides of the fingers 70 and 71 are 7

provided with V-shaped grooves for lockingly engaging the opposite edges of the projection 64. By this arrangement, the clutching element 65 may be held clutched to the projection 64 even though the magnet 72 is deenergized, so long as the energized one of the magnets 23 and 24 is not deenergized.

In the operation of the switching unit described above and with the elements thereof in the positions illustrated in Figs. 1, 2, 3 and 4, if it be desired to connect the lines outgoing therefrom which terminate at the set of wipers including the wipers 51, the magnet 72 is first energized to bring the actuating member 18 into driving relationship with the shaft 37. Thus, when the magnet 72 is energized, it attracts its armature 76 to make contact between the two springs of the assembly 81 and to pivot the arm 77 counterclockwise, thereby to slide the clutching element 65 along the shaft 37 against the bias of the spring 67 until it stands in a position such that the fingers 70 and 71 of the clutching element 65 have extending therebetween the projection 64 mounted on the actuating member 18. From a consideration of Figs. 3 and 4, it will be seen that the contact segments 40 must be rotated in a counterclockwise direction in order to connect the lines incoming to the unit to the outgoing lines terminating at the wipers 51. This means of course, that the actuating member 18 must be moved to the right from the position shown in Fig. 4 and to the left from the position shown in Fig. 1, and consequently requires that the operating magnet 23 be energized. When this occurs, the finger 64 engages with the finger 76 of the clutching element 65 to rotate the shaft 37 in a counterclockwise direction and bring the contact segments 40 into engagement with their respective associated wipers 51, thereby to connect the lines incoming to the unit to the lines terminating at these wipers. The operating magnet 24 is maintained energized so long as the connection between these lines is desired. To restore the elements of the unit to normal, it is only necessary to deenergize the magnet 24, whereupon the clutching element 65 is disengaged from the actuating member 18 under the force exerted by the spring 67 subsequent to the return of the member 18 to its normal position by virtue of the force exerted thereon by the spring 28. As explained above, when the clutching element 65 is disengaged from the actuating member 18, the shaft 37 and the commutating segments 40 carried thereby are restored to their normal positions through the force exerted on the shaft 37 by the spring 61. From the preceding description, it will be understood that, if it is desired to connect the lines incoming to the switching unit to the lines outgoing therefrom which terminate at the wipers 52, the exact sequence of operations described above is followed with the exception that the operating magnet 24 is energized rather than the magnet 23.

As noted previously, the actuating member 18 is arranged selectively to operate the circuit controlling elements embodied in all of the switching units mounted within the section 11 of the frame 10. This is accomplished by providing projections, corresponding to the projection 64 for the unit 13, at correctly spaced intervals along the actuating member 18, which projections are adapted individually to cooperate with clutching elements individually included in each of the switching units and corresponding to the element 65 of the unit 13, when the units are mounted in

their correct positions within the section 11 of the frame 10.

Referring now more particularly to Figs. 5 to 10 of the drawings, there is illustrated an automatic telephone system connected and arranged in accordance with the present invention and having embodied therein switching apparatus of the form just described. In general, the system comprises a plurality of telephones or subscribers' substations, three of which are indicated at A, B and C, adapted to be interconnected by means including their respective associated lines 111, 220 and 211, and finder-connector links of the form illustrated. While these links may be designed to serve any desired plurality of lines, it is specifically contemplated that the links, corresponding to and including the link illustrated, will have access to and be accessible to one thousand subscribers' lines. These lines are divided into ten one hundred line groups, numbered consecutively from one to zero, and, as outlined above and pointed out in greater detail hereinafter, the mode of line selection in both the finder and connector portions of each link is predicated on the odd and even numbers identifying the various line groups. The number of finder-connector links to be provided obviously will depend upon the telephone traffic to be handled over the plurality of lines terminating thereat. In any case, it will be understood that each subscriber's line is multiplied to the corresponding bank conductors of the finder and connector switches embodied in a plurality of links. For the purpose of allotting the links to successive calling lines in a definite order, there is provided the allotter means illustrated in Fig. 7. This means, as will be pointed out with greater particularity hereinafter, operates in a manner such that an idle link is always in readiness for instant seizure by a calling line. A further general feature of the arrangement illustrated pertains to the provision of control means in the connector portion of each link for testing any selected called line to determine the idle or busy condition thereof, for applying busy tone current to the calling line in the event the selected called line is found busy and for connecting the calling line to the called line in the event the called line is found idle. An additional general feature of the arrangement is concerned with the provision of means whereby automatic trunk hunting occurs in the connector portion of each link upon the dialing of a predetermined digit at the substation of a calling party having a line terminating at the links.

Neglecting for the present the details of the finder and connector switches, the allotter means, and the control means respectively included therein, the system as briefly described immediately above is, in general, quite similar to conventional prior art systems, the operation of which is well understood in the art. In brief, when a subscriber, such, for example, as the subscriber at the telephone A, initiates a call over the line 111 to a second subscriber's telephone, such, for example, as the telephone B, by lifting his receiver from its hook, the finder-connector link, previously assigned by the allotter means illustrated in Fig. 7, is started in operation to search for and seize the calling line. Assuming that the link illustrated is delegated by the allotter means to set up the connection, the finder portion of the link operates to select the calling line and to connect it through to the link conductors leading to the connector portion of the

switch. When the calling line is seized and extended by way of the finder switch to the associated connector switch, the control equipment of the last-mentioned switch is automatically conditioned to be responsive to the first series of impulses transmitted from the impulsive device conventionally provided at the substation A.

In response to the dialing of the first digit at the substation A, the connector portion of the link operates to select a group of lines including the called line 220. Thereafter and in response to the dialing of the second digit, a subgroup of lines including the called line is selected from the selected group of lines and, at the conclusion of this digit, the control equipment of the connector switch is conditioned to respond to the third or final series of impulses dialed at the calling substation. With the link in this condition and when the third or final digit is dialed, the connector switch operates to select the called line from the selected subgroup including the same and to test the condition thereof to determine its idle or busy condition.

If the called line is found busy, busy tone current is applied to the loop extending to the calling subscriber's substation, whereas, if the called line is idle at the time it is selected, ringing current is automatically applied thereto and ring-back tone current is applied to the loop extending to the calling subscriber's substation. Finally, the connection between the calling and called lines is completed when the called substation B is answered. As pointed out in detail hereinafter, the arrangement is such that a link utilized in setting up a desired connection is released only when both the calling and called parties have restored their respective receivers to the associated hooks.

In the use of the link to select a trunk line terminating in the bank conductors of the connector portion thereof and outgoing to a distant exchange, only two predetermined digits need be dialed at the calling substation. The impulses comprising these two digits, when received at the connector portion of the link, cause a subgroup of lines consisting solely of trunk lines to be selected, and condition the apparatus normally operative to select a particular called line to function in the manner of a trunk hunting selector switch. Immediately, the series of impulses comprising the second digit is concluded, this last-mentioned apparatus is started into operation in search of an idle one of the trunk lines. When an idle trunk is found, the trunk hunting operation is interrupted and the calling line is extended by way of the idle trunk to the terminating apparatus located at the distant end of the seized trunk. The arrangement is such that all voice-frequency coupling elements, such, for example, as condensers, are eliminated from the conversational circuit when this circuit includes one of the trunk lines. The release of a link involved in a connection extended by way of one of the trunk lines is under the control of the apparatus at which the distant end of the trunk terminates.

Considering now the particular construction and arrangement of the apparatus comprising the features of the present invention, it is pointed out that the finder means of each link comprises a plurality of switching units 505, 506, etc., mounted in a frame 504 and including control elements 507, 508, etc., arranged to be operatively associated with an operating member 515 through the medium of means individually embodied in the units and comprising clutches 509,

514, etc., and clutch magnets, one of which is indicated at M520 for the unit 505. It will be understood from the preceding description that each of the units 505, 506, etc., is identical with the unit described above with reference to Figs. 5 1 to 4, inclusive, and that the frame 504 corresponds to the frame 10 shown in Fig. 1. Each of the switching units 505, 506, etc., like the corresponding unit shown in Fig. 2, includes two sets of bank conductors or wipers oppositely disposed 10 with respect to the contact segments carried by the control element embodied in the unit, and having terminating thereat a number of the lines of the system. It is contemplated that each of these sets shall contain sixty conductors so that 15 twenty, three-conductor lines, may be terminated thereat. Thus, each switching unit has extending thereto forty lines, with the result that twenty-five units are required in each finder switch for the termination of the one thousand 20 lines extending thereto. It is noted here that the twenty lines extending to one set of blank conductors embodied in each switch are included in an odd numbered group of one hundred lines and that the twenty lines extending to the other set 25 of bank conductors of the same switch are included in the next succeeding even numbered group of one hundred lines. Thus, the switch 505 has extending to its bank conductors, indicated to the left of the control element 507, the lines numbered from 110 to 129, inclusive, and the group of bank conductors, indicated to the right of the control element 507, have terminated thereat the conductors of the lines numbered from 210 to 30 229, inclusive. As noted above, the conductors of 35 the various lines extending to the finder switch illustrated are, in accordance with conventional practice, multiplied to the corresponding bank conductors embodied in the switching units of the other finder switches.

As pointed out in the introductory portion of the specification, the method by which the finder switch shown operates to select a particular calling line includes the step of simultaneously selecting two groups containing one hundred lines 40 each. This is accomplished through the operation of means comprising a rotary stepping switch 602 which is responsive to the initiation of a call, on one of the lines extending to the finder switch and which functions to select a group of the 45 switching units 505, 506, etc., to which extend two groups of lines one of which includes the calling line. More specifically, the operation of the switch 602 is controlled by the line relay associated with a calling line, the gang relay R580 as 505 sociated with the link illustrated, and certain of the relays included in the allotter means. Selection of the group of units is accomplished through the operation of the switch 602 to prepare circuits for energizing the clutch magnets individually included in the units comprising the selected group.

Selection of the subgroup of lines which includes the calling line is obtained through the operation of means comprising the rotary stepping switch 612 to select the one of a group of units, selected by the switch 602, to which the calling line extends and to determine the direction of movement of the control element embodied in the selected unit in accordance with 70 the odd or even number identifying the group of lines including the calling line. The switch 612 is, in operation, controlled by certain of the relays embodied in the allotter means, which relays are in turn controlled by circuits extending by 75

way of the two switches 602 and 612 and the line relay associated with a calling line responsible for the seizure of the link. Selection or determination of the direction of movement of the control element of a selected switching unit is accomplished through the operation of the switch 612 to prepare a circuit for energizing one or the other of the operating magnets M540 and M550 associated with the operating member 515 and corresponding, respectively, to the odd numbered groups of lines and the even numbered groups of lines. These magnets comprise means for actuating the operating member 515 to move any control element operatively associated therewith in either of its two directions of movement, which means is, through the control exerted thereon by the relays embodied in the allotter means, only operative following the energization of one of the clutch magnets.

As noted above, the proper selection of a particular switching unit, followed by the operation of its control element to the selected off-normal position, causes a subgroup of lines including the calling line to be selected. These lines are extended by way of the contact segments carried by the control element of the selected unit to the bank contacts of a rotary switch 538, which forms a part of means for selecting the particular calling line from the selected subgroup of lines. This switch comprises six contact sets of ten contacts each, and of these contact sets the three upper sets have connected thereto ten of the contact segment sets of each of the twenty-five switching units embodied in the finder switch and the three lower contact sets have connected thereto the remaining ten contact segment sets of each of the switching units. By this arrangement, and when a selected switching unit is operated, twenty lines, divided into two small subgroups of ten lines each, are extended to the bank contacts of the switch 538, so that this switch may operate simultaneously to test the lines in pairs until the calling line is found. If the calling line is included in one ten-line group and when this line is found, a polarized relay R570 is caused to operate to switch the line conductors thereof through to the line conductors C117, C119 of the link line extending to the switch 538. If, on the other hand, the calling line is included in the second smaller subgroup of ten lines, a polarized relay R560 is caused to operate to connect the line conductors thereof to the link line conductors noted.

The line selecting means embodied in the connector portion of each link is, from the standpoint of the apparatus involved, quite similar to that included in each of the finder switches, as briefly described above. Thus, the connector switch shown comprises twenty-five switching units 1013, 1014, etc., of the form shown in Figs. 2 and 3, mounted in a frame 1012 and having commonly associated therewith an operating member 1019 under the control of means comprising two operating magnets M1020 and M1030, corresponding, respectively, to the odd numbered groups of lines and the even numbered groups of lines. Each of these units includes a circuit controlling element, corresponding to the element 37 of the unit shown in Figs. 2 and 3, that for the unit 1014 being indicated at 1016, normally non-operatively associated with the operating member 1019 and arranged operatively to be associated with this member by clutch means comprising a clutch and a clutch magnet, these two elements for the unit 1014 being indicated at 1018

and M1010, respectively. Forty subscribers' lines are terminated at each switching unit, twenty of these lines extending to the bank conductors of one of the two bank conductor sets embodied therein, and twenty extending to the bank conductors of the other bank conductor set. These two twenty line subgroups terminated at each unit are respectively included in consecutively numbered odd and even groups of lines. For example, the lines extending to the conductor set 10 of the unit 1014 indicated to the right of the shaft 1016 are consecutively numbered from 210 to 229, whereas, the lines extending to the conductor set indicated to the left of the shaft 1016 are consecutively numbered from 110 to 129. 15

For the purpose of selecting a group of one hundred lines which includes a desired called line, there is provided means comprising a rotary switch 1042, which responds to the first series of impulses transmitted to the connector switch 20 and functions to select the group of switching units to which the lines of the group of lines including the called line extend. Thus, with the wipers of the switch 1042 standing in any off-normal position, five switching units are tentatively selected by virtue of the preparation of circuits for energizing the clutch magnets respectively embodied therein. The means noted, namely that comprising the switch 1042 further operates, in accordance with the odd or even 30 number identifying the group of lines including the called line, to determine which of the two magnets M1020 and M1030 is to be subsequently energized, thereby to determine the direction of movement of the control element embodied in 35 the switching unit which is ultimately selected.

The selection of the subgroup of lines including the called line is accomplished through the operation of means responsive to the second series of impulses transmitted to the connector switch 40 and comprising a rotary stepping switch 1002 which functions to select the particular switching unit to which the called line extends by further preparing the operating circuit for the clutch magnet embodied therein. Thus, this 45 switch, through the operation of its wiper SW1004 to a particular off-normal position, determines the one of the five clutching magnets, selected by the operation of the switch 1042, which is to be energized, and thereby selects the 50 one of the switching units which is to be operated upon the subsequent energization of one or the other of the magnets M1020 and M1030. This switch also functions to control the wiper switching relay R960 in the manner pointed out here- 55 inafter.

The contact segments carried by the control element of each unit are connected to the contacts of the contact sets included in a rotary switch 974, which switch responds to the third 60 series of impulses transmitted to the connector switch and, in conjunction with the wiper switching relay R960, comprises means for selecting a desired line from a selected subgroup of lines. In this connection, it will be appreciated 65 that, with any one of the switching units operated to one of its two off-normal positions, twenty lines will be connected to the bank contacts of the rotary switch 974 so that when this switch is subsequently caused to operate it functions to select the called line from the subgroup of twenty lines extended thereto. 70

As pointed out above, each of the links further includes means for testing a selected called line to determine its idle or busy condition, for ap- 75

plying busy tone current to the calling line in the event the called line is found busy, for applying ringing current to the called line and ring-back tone current to the calling line in the event the called line is idle, and for connecting the calling line to the called line in the event the called line is idle and the called substation is answered. This means comprises the busy relay R940, the ringing relay R850, the ring cut-off relay R930, and a slave relay R850, together with the operating circuits therefor. Additional relays R810, R820, R830, R840, R850, R860, R870, R900, and R910 are provided in each link for controlling the operation of the various rotary switches and relays referred to above, all in the manner described with particularity hereinafter. It is noted here that each of the relays embodied in the apparatus shown is of standard commercial construction and is conventionally indicated in the drawings in accordance with the operating characteristic which it possesses.

The allotter means, illustrated in Fig. 7, comprises, in addition to the relays R710, R720, R730, R740, R750, R760, and R770 for controlling the operation of any seized finder-connector link, a rotary stepping switch 702 which, in combination with certain of the relays noted, functions to allot the links to successive calling lines. This stepping switch, together with the other switches of similar type, corresponding to and including the enumerated switches 538, 602, 612, 974, 1002 and 1042, may be of any standard commercial construction which comprises bank contacts arranged in sets, wipers respectively associated with the contact sets, and means comprising a motor magnet for driving the associated wipers. Certain of these rotary switches, namely the switches included in the connector portion of each link, include off-normal springs which are utilized during the release of the links to return the switches respectively embodying the same to normal.

As pointed out previously, the connector portion of each link may be arranged to perform trunk hunting operations upon the dialing of a predetermined number at a calling subscriber's substation. More specifically, this operation is obtained with the link illustrated when a calling subscriber dials the number 01. This causes the rotary switch 1042 to be operated to its tenth off-normal position and the switch 1002 to operate to its first off-normal position thereby to cause the rotary switch 974 repeatedly to operate under the control of means comprising the two relays R910 and R920 until an idle trunk in a group of trunks outgoing to a distant exchange is found. The finding of such a trunk is followed by the operation of R800 which stops the trunk hunting operation of the connector switch and switches the calling line through by way of the selected trunk to the distant exchange.

Operation of a finder switch to find a calling line in an odd-numbered group of one hundred lines

Referring now in greater detail to the operation of the apparatus to establish a connection between the lines 111 and 220 on a call from the substation A to the substation B, operation of the finder switch illustrated in Figs. 5 and 6 is initiated when the calling party at the substation A lifts his receiver from its hook to complete a circuit for energizing the line relay R500. The circuit noted extends from ground at RA512 by way of C100, the direct current bridge across

the line conductors C100 and C101 at the substation A, C101, RA511 and through the winding of R500 to battery.

When R500 operates in response to its energization over the above-traced circuit, it marks, at RA501, the calling line in the bank conductors of the switch unit 505 by extending battery from the cut-off relay R510 to the bank conductor 524. At its armature RA502, the relay R500 prepares a circuit, traced hereinafter, for energizing R750 included in the allotter means illustrated in Fig. 7. At its armature RA503, the relay R500 applies ground to C106 to mark, in the contact set associated with SW608, the contact corresponding to the group of one hundred lines which includes the calling line 111. The operation of RA503 also completes a circuit for energizing R710 embodied in the allotter means illustrated in Fig. 7, this circuit extending from ground at RA503 by way of C106, C151, RA741, the winding of R710, MA701 and through the winding of M700 to battery. Due to the high resistance of the winding of R710, the magnet M700 included in the rotary switch 702 does not operate. The relay R710, however, operates to complete, at RA712, an obvious holding circuit for itself, and to complete, at RA711, a circuit for energizing the upper windings of R750, R760 and R770. The last mentioned circuit extends from ground at RA711 to C158, where it divides, one branch extending through the upper winding of R770 to battery, and the other branch extending through the upper windings of R760 and R750 in series to battery. The three relays noted are of the polarized type and do not operate in response to the energization of their respective upper windings, such energization only being effective to render these relays exceedingly fast to operate when their respective lower windings are subsequently energized. The relay R710 also completes, at RA713, a circuit for energizing R580, this circuit extending from ground at RA713 by way of SW703, C131 and the winding of R580 to battery.

As noted previously and pointed out in greater detail hereinafter, the rotary switch 702 functions to allot the various finder connector links to successive calling lines in a definite order. The arrangement is such that SW703 always stands in engagement with an associated contact corresponding to an idle finder connector link. Thus, in the present assumed case, wherein the link illustrated is idle at the time the call is initiated on the line 111 and is selected by the allotter as the link for use, SW703 stands in engagement with the contact corresponding to this link so that the link is seized immediately upon operation of R710.

When energized over the above-traced circuit, R580 operates to complete at RA583 a circuit for energizing the respective lower windings of R560 and R570 in series, thereby to render these relays, which are of the polarized type, exceedingly fast to operate when their respective upper windings are subsequently energized. The circuit noted extends from ground at RA583 through the two windings noted to battery. At its armatures RA581 and RA582 the relay R580 prepares circuits for energizing the respective upper windings of R560 and R570. At RA594, the relay R580 completes a circuit for energizing M600 included in the rotary switch 602, this circuit extending from ground at RA721 by way of C159, RA751, RA761, RA771, RC772, C132, RA594, C130, and through the winding of M600 to battery. The magnet M600, upon being energized over the

above-traced circuit, prepares the switch 602 to step the switch wipers embodied therein one step and completes, at MA601, a circuit for energizing R720. The last-mentioned circuit extends from ground at MA601 by way of C128, RA593, C133 and through the upper winding of R720 to battery. The relay R720 now operates to interrupt, at RA721, the above-traced operating circuit for M600 causing this magnet to be deenergized, whereupon the switch wipers of the switch 602 are stepped one step or into engagement with the respective first contacts of their respective associated contact sets. When M600 is deenergized to restore MA601, the above-traced operating circuit for R720 is interrupted so that the operating circuit for M600 is again completed at RA721. This interrelated operation of R720 and M600 continues until SW608 is moved into engagement with the contact corresponding to the group of switching units including the unit at which the calling line 111 terminates.

In the present case, wherein the calling line is included in the No. 1 group of one hundred lines, terminating at the group of units including the unit 505, the switch wipers of the switch 602 are stepped only one step. When this occurs, a circuit is completed for energizing R710 included in the allotment means, this circuit extending from ground at RA503 by way of C106, the second contact of the contact set associated with SW608, C121, RA581, C134, and through the lower winding of R710 to battery. The relay R710 immediately operates, to interrupt, at RA711 and RC712, the above-traced circuit for M600 and to complete, at RA711 and RC713, a circuit for energizing M610 embodied in the rotary switch 612. The last-mentioned circuit extends from ground at RA721 by way of C159, RA751, RA761, RA771, RC713, C135, RA590, C126 and through the winding of M610 to battery.

Before describing the operation of the rotary switch 612, it is pointed out that the operation of the rotary switch 602 to select the group of units including the unit at which the calling line terminates, completes a path for marking, in the bank contacts of the switch 612, the particular unit of the selected group at which the calling line terminates and for identifying the odd or even number of the group of lines, terminating at the selected group of units, which includes the calling line. This path extends from ground at RA592 by way of C128, SW609, the second contact of the contact set associated with SW609, C105, RA502, C107, to the second contact of the contact set associated with SW614. The application of ground to the last-mentioned contact identifies the calling line as terminating at the switching unit 505 and further as being included in the No. 1 group of one hundred lines rather than the No. 2 group of one hundred lines. The switch 602 further operates to prepare the operating circuits for the clutch magnets embodied in the selected group of switching units. Thus, with the switch wipers SW603 to SW607, inclusive, standing in engagement with the respective second contacts of their respective contact sets, circuits are prepared for energizing the clutch magnets of the five switching units making up the selected group of units. These circuits extend by way of the conductors corresponding to and including C143 which terminate at the respective second contacts of the contact sets noted.

Continuing now with the operation of the rotary switch 612, when M610 is energized over the above-traced circuit, it attracts MA611 to

complete a circuit for energizing R720, this circuit being identical with that traced above in connection with the operation of the switch 602, with the exception that it extends from ground at MA611 rather than from ground at MA601 associated with M600. The resulting operation of R720 causes the interruption of the operating circuit for M610, at RA721, in the same manner as was described above for the magnet M600. Thus, R720 and M610 interact upon each other to cause the switch wipers of the switch 612 to be stepped until the switching unit included in the selected group of units and having the calling line extending thereto is found. In the present assumed case, wherein the calling line is included in the subgroup of twenty lines terminating at the unit 505 and included in an odd numbered group of one hundred lines, the switch wipers of the switch 612 will be moved only one step at which time a circuit is completed for energizing the lower winding of R750. This circuit extends from ground at RA592 by way of C128, SW609, C105, RA502, C107, SW614, C124, RA588, C137, RA763 and through the lower winding of R750 to battery. In response to the energization of its lower winding, R750 immediately operates to interrupt, at RA751, the operating circuit for M610, thereby to stop the rotary switch 612. With M600 and M610 deenergized, the operating circuit for R720 is opened at MA601 and MA611 so that this relay also remains deenergized. At this point, it will be noted that the switching unit 505 at which the calling line terminates is selected and that the direction of movement of its control element 507 to connect the lines of the subgroup including the calling line to the bank contacts of the switch 538, is determined. Thus, immediately upon the operation of R750, a circuit is completed for energizing M520 embodied in the switching unit 505, this circuit extending from ground at RA754 by way of C138, RA587, C123, SW613, SW603, C143 and through the winding of M520 to battery. This magnet, which corresponds to the magnet 72 illustrated in Fig. 2 of the drawings, attracts its armature MA521, thereby operatively to associate the control element 507 of the switch 505 with the operating member 515 through the medium of the clutch 509. Simultaneously with the energization of M520, an obvious circuit is completed at RA752 for energizing the slow-to-operate relay R740 and, shortly after the operation of the clutch magnet M520, the last-mentioned relay operates to complete a circuit for energizing M540 associated with the operating member 515. This circuit extends from ground at RA743, by way of RA755, RC756, C139, RA586 and through the winding of M540 to battery.

The magnet M540, upon being energized, attracts to the left the armature carried by the operating member 515, thereby to rotate the control element 507 and bring the contact segments carried thereby into engagement with the contact wipers shown to the left to the control element. At MA541, the magnet M540 prepares a holding circuit for itself which is completed upon the subsequent operation of R560 or R570. With the contact segments of the switch 505 standing in engagement with the wipers shown at the left of the shaft 507, the subgroup of twenty lines terminating at these wipers are connected by way of the contact segments engaging respectively therewith, to the bank contacts of the rotary switch 538, as indicated by the lines 238 and 231. This subgroup of twenty lines includes

75

the lines 110 to 119, inclusive, and 120 to 129, inclusive. By this operation, the line conductors C100 and C101, and the test conductor C104 are extended by way of switch wipers 522, 523 and 524, respectively, the contact segments 516, 517 and 518, respectively, and the conductors C107, C108, and C109, respectively to the respective second contacts of the contact sets associated, respectively, with SW532, SW533 and SW534, embodied in the rotary switch 538.

10 Simultaneously with the energization of M540, an obvious circuit is completed at RA742 of R740 for energizing the slow-to-operate relay R730, and, shortly after the control element 507 has been rotated to extend the calling line to the bank contacts of the rotary switch 538, the relay R730 operates to complete, at RA734, a circuit for energizing M530 embodied in the rotary switch 538. This circuit extends from ground at RA721 by way of C159, RA734, C141, RA584, RA575, RA569' and through the winding of M530 to battery. In response to its energization over the above-traced circuit, M530 attracts its armature MA531 to complete a circuit extending by way of RA593 and C133 for again energizing R720. The relay R720, upon operating, interrupts, at RA721, the operating circuit for M530 which in turn restores MA531 to interrupt the operating circuit for R720. Thus, M530 interacts with R720, in a manner similar to that described above with reference to M600 and M610, to cause the switch wipers of the switch 538 to be stepped until the switch wipers SW532, SW533 and SW534 stand in engagement with the associated contacts to which the line conductors of the calling line 111 extend. In the present assumed case, wherein the calling line is the first line in the first subgroup of lines in the first one hundred line group, the switch 538 will be caused to take only a single step, at which time a circuit is completed for energizing the upper winding of R570, this circuit extending from battery at the cut-off relay R510 by way of RA501, C104, switch wiper 524, contact segment 518, C109, SW534, C112, and through the upper winding of R570 to ground at RA581. The relay R570 immediately operates to interrupt, at RA575, the operating circuit for M530, causing this magnet and R720 to remain deenergized. At RA574, the relay R570 completes a holding circuit for M540, which circuit extends by way of the resistor 576, MA541, and through the winding of M540 to battery, and holds the magnet noted energized independently of the apparatus included in the allotter means. At its armature RA573, the relay R570 completes a path for short-circuiting its upper winding and a circuit for energizing the cut-off relay R510. The path noted extends from ground at RA583 by way of RA568, C120, RA573, and the upper winding of R570, back to ground at RA581, and the upper winding of R570 to battery. The relay R570 extends over the same path to RA573, where it branches to extend by way of C112, SW534, C109, the contact segment 518, the switch wiper 524, C104, RA501, C103 and through the winding of R510 to battery. The relay R570 does not restore when its upper winding is short-circuited, but remains operated due to the continued energization of its lower winding over the path described previously. At its armatures RA571 and RA572, the relay R570, upon operating, connects the line conductors C100 and C101 of the calling line 111 through to the link conductors C117 and C119, respectively in an obvious manner.

75 It is noted here that the application of ground

to C103 to cause the energization of R510 also marks the calling line 111 as busy in the bank conductors of the connector switches to which this line extends. The cut-off relay R510, upon being energized over the above-traced circuit, operates to interrupt, at RA511 and RA512, the previously traced operating circuit for the line relay R500 and to shunt, at RA513, the armature RA501 of the line relay R500, thereby to hold itself energized when R500 restores. When R500 restores, it interrupts, at its armatures RA502 and RA503, the operating circuits for the relays R710, R750 and R770 included in the allotter means. When R710 restores, it interrupts, at RA711, the holding circuits for R750 and R770, causing these two relays to restore, and, at RA713, it interrupts the operating circuit for R580, causing this relay to restore. When R750 falls back, it interrupts, at RA754, the operating circuit for M520 and, at RA752, the operating circuit for R740. Shortly following the restoration of R740 and the resulting deenergization of R730, the last-mentioned relay restores. Thus, all of the relays included in the allotter means are restored to normal. The deenergization of M520 embodied in the switch 505 does not result in the unclutching of the control element 507 from the operating member 515 since, as was pointed out above, with this member actuated to an off-normal position, the shaft 507 is locked clutched thereto.

Before the line relay R500 restores, and immediately upon the operation of R570, a circuit is completed for energizing R810 embodied in the connector portion of the link, this circuit extending from ground at the lower winding of the relay noted by way of C168, RC807, RA805, C119, RA564, RC565, C118, RA572, C111, SW533, C108, C101, the direct current bridge across the line conductors C101 and C100 at the substation A, C100, the switch wiper 522, the contact segment 516, C107, SW532, C110, RA571, C116, RC562, RA561, C117, RA801, RC802 and through the upper winding of R810 to battery. When energized over the above-traced circuit, the relay R810 operates to complete, at RA811 and RC812, an obvious circuit for energizing the slow-to-release hold relay R830. The last-mentioned relay, upon operating, applies, at RA833, ground to C122, thereby to provide a holding circuit for R570 which is independent of the condition of R580. It is noted that R830 is caused to operate before the line relay R500 falls back, whereby the connection as extended from the calling line to the link line conductors C117 and C119 is maintained.

Operation of a finder switch to find a calling line in an even numbered group of lines

Before describing the operation of the connector portion of the link and in order to complete the description of the operation of the finder portion thereof, it will be assumed that the calling line is included in an even numbered group of one hundred lines. To this end it will be assumed that the line 220 is the calling line instead of the line 111, and that the link illustrated is started in operation to search for this line in response to the operation of the line relay associated therewith. This line relay, upon operating, marks the calling line 220 in the bank conductors of the switch 505 and applies ground to C106, all in the exact manner described above with reference to the line relay R500 associated with the line 111. The operation of the line relay associ- 75

ated with the line 220 also causes a circuit to be prepared by way of the conductor, corresponding to C107, for controlling the operation of the rotary switch 612. In the present instance, the conductor noted, namely that corresponding to C107, terminates at one of the contacts included in the contact set associated with SW615 instead of at a contact in the set associated with SW614. This different termination of the conductor noted identifies the calling line as being included in an even numbered group of lines rather than in an odd numbered group of lines.

Thus, when the switch 602 has completed its operation to select the group of switching units to which extend the groups of lines, one of which includes the calling line, and R770 has, as a result, operated, the switch 612 is started in operation, in the manner described previously, in search of the switching unit to which extend the subgroup of lines including the line 220. Since, in the last assumed case, this unit corresponds to the second contact of the contact set associated with SW615, a circuit is completed, upon SW615 encountering this contact, for energizing R760, this circuit extending from ground at RA592 by way of C128, SW609, C105, the relay armature, corresponding to RA502, embodied in the line relay associated with the line 220, the above-noted conductor corresponding to C107, the second contact of the contact set associated with SW615, C125, RA589, C136, RA753 and through the lower winding of R760 to battery. With its lower winding energized, R760 immediately operates to interrupt the operating circuit for M610, thereby to discontinue the interrelated operation of this magnet and R720. At RA764, the relay R760, upon operating, completes a circuit for energizing M520, this circuit being identical with that traced previously for the magnet noted with the exception that it starts from ground at RA764 rather than from ground at RA754. At RA765, the relay R760, upon operating, prepares a circuit for energizing the operating magnet M550 associated with the operating member 515 and, at RA762, it completes an obvious circuit for energizing R740. The last-mentioned relay operates, after an interval, to complete, at RA743, the above-noted circuit for energizing M550, causing this magnet to operate and rotate the control element 507 to bring the contact segments carried thereby into engagement with their respective associated wipers indicated to the right of the element 507. The circuit noted, namely that for M550, extends from ground at RA743 by way of RA755, RA757, RA765, C140, RA585 and through the winding of M550 to battery. The magnet M550 not only operates the operating member 515 to its right off-normal position but it also prepares, at MA551, a holding circuit for itself extending from ground at RA569, which circuit is completed upon the subsequent energization and operation of R560 or R570.

The relay R740, upon operating, not only completes the above-noted circuit for M550 but also completes, at RA742, an obvious circuit for energizing R730. The last-mentioned relay operates after an interval to complete, at RA734, the previously described operating circuit for M530, embodied in the rotary switch 538. This magnet is now caused to operate and interacts with R720 to cause the wipers of the switch 538 to be stepped until SW537 encounters the associated contact corresponding to the calling line 220; which contact is identified by the pres-

ence of battery thereon from the cut-off relay associated with the calling line. When this occurs, an obvious circuit is completed for energizing the upper winding of R560, which relay immediately operates to interrupt, at RA569, the operating circuit for M530, thereby to discontinue the interrelated operation of M530 and R720. At RA567, the relay R560 short-circuits its upper winding from ground at RA583 and completes a circuit for energizing the cut-off relay associated with the calling line 220, this circuit being similar to that traced above for the cut-off relay R510 associated with the line 111. At RA569, the relay R560 completes an obvious holding circuit for M550 and at its armatures RA561 and RA564 and their respective associated contacts RC563 and RC566, it connects the line conductors of the calling line 220, which have now been extended to the bank conductors of the switch 538, to the link line conductors C117 and C119 leading to the connector portion of the link. The operations which occur following the energization of R560 are exactly the same as those described above following the operation of R570 in the assumed case wherein the line 111 was the calling line. Briefly summarized, these operations comprise the operation of R810 embodied in the connector portion of the link, followed by the operation of R830 and the application of holding ground to C122, thereby to maintain the finder switch illustrated and the cut-off relay associated with the calling line operated independently of R580 and the apparatus included in the allotter means as illustrated in Fig. 7. The operation of R560 is also followed by the restoration of the line relay associated with the line 220 and the subsequent restoration of the operated relays included in the allotter means.

From the foregoing description, it will be apparent that the group of one hundred lines including the calling line is marked by the application of ground to one of the five start conductors C106, C144, C145, C146 and C147. If the calling line is in the first or second one hundred line group, ground is applied to C106; if the calling line is in the third or fourth one hundred line group, ground is applied to C144; if the calling line is in the fifth or sixth one hundred line group, ground is applied to C145; and so on. Strictly speaking, the application of ground to any one of the enumerated start conductors only identifies the calling line as being included in one large group of two hundred lines since it determines the group of five switching units to be selected by the rotary switch 602. The termination of the conductor extending to the line relay and corresponding to C107, however, determines whether the calling line is in the odd or even group of one hundred lines. Thus, as was pointed out above, if the calling line is included in an odd numbered group of lines, the conductor extending to one of the springs of the line relay associated with the calling line and corresponding to C107 is terminated at one of the contacts of the contact set associated with SW614. If, on the other hand, the calling line is included in an even numbered group of lines, this conductor is terminated at one of the contacts included in the set associated with SW615. It will further be apparent, in view of the preceding description, that the rotary switch 612 not only comprises means for selecting from the group of units selected by the rotary switch 602, the particular switching unit to which the calling line extends, but also functions to determine

the direction of rotation of the control element embodied in the selected unit in accordance with the odd or even number identifying the group of lines which includes the calling line. The subsequent rotation of the shaft embodied in the switch 505, or a corresponding switch, in one direction or the other results in the selection of the subgroup of twenty lines including the calling line, and finally the operation of the rotary switch 538 results in the selection of the calling line from the selected subgroup of lines.

Operation of a connector switch to select a called line in an even numbered group of lines

Continuing now with the operation of the connector portion of the link illustrated, when R830 operates, it completes, at RA834, a circuit for energizing R900, this circuit extending from ground at the armature noted by way of C180 and the winding of R900 to battery. At RA836, the relay R830 applies ground to C142, thereby to complete a circuit for energizing M700 included in the rotary switch 702 of the allotter shown in Fig. 7. This circuit extends from ground on the conductor noted by way of SW704, C162, RA732, RC733, C160, MA701 and through the winding of M700 to battery. Due to the self-interrupting contacts associated with MA701, the magnet M700 operates buzzer fashion and drives the switch wipers SW703 and SW704 until the last-mentioned wiper stands in engagement with an associated contact, corresponding to an idle one of the links. It will be apparent from the foregoing that a busy link is identified by the presence of ground on the conductor individually associated therewith and corresponding to C142, whereas, if a link is idle, the conductor associated therewith and corresponding to C142 is open-circuited. Hence, when SW704 encounters a contact, corresponding to an idle link, the above-traced operating circuit for M700 is interrupted and the operation of the switch 702 is arrested. With the respective switch wipers of the switch 702 standing in a position corresponding to an idle link, a circuit is prepared by way of SW703 for energizing the relay in this link which corresponds to R580 embodied in the link illustrated. As a consequence, this relay will be energized in response to the initiation of a call on the next succeeding calling line, thereby to cause the seizure of the selected idle link.

When R900 operates, following the operation of R830, it applies, at RA901, dial tone current to the loop extending to the calling subscriber's substation, thereby to indicate to the calling party that the apparatus embodied in the seized link is conditioned to be responsive to impulses transmitted from the impulsive device located at the substation A. Operation of R900 also prepares holding circuits, traced hereinafter, for the ring cut-off relay R930, the ringing relay R950 and the busy relay R940. The apparatus embodied in the connector portion of the switch is now in readiness to respond to impulses transmitted from the calling subscriber's impulsive device.

At the beginning of the first impulse of the first digit dialed at the calling subscriber's substation when the impulsive springs of the impulsive device located thereat are opened, the operating circuit for R810 is opened causing this relay to restore to complete, at RA811, a circuit for energizing R840 in series with M1040 embodied in the rotary switch 1042. This circuit extends from ground at RA811 by way of RC813,

RA835, C182, RA958, C183, the winding of R840, C189, RA866, RC868, RA877, C188 and through the winding of M1040 to battery. The relay R840, upon operating, completes, at RA842, an obvious circuit for energizing R850 and, at RA841, a circuit extending by way of RA861 and RC862 for energizing the lower winding of R860. The last-mentioned relay is constructed to operate in two steps; that is, it operates only R864 when its lower winding is energized and assumes its fully operated position only when its upper and lower windings are subsequently energized in series. With R850 operated, the upper winding of R860 is short-circuited over a path extending from ground at RA855 by way of RA864, the upper winding noted, RA861, RC862, and back to ground at RA841. Thus, R860 remains in its partially operated condition during the impulses comprising the first digit.

When M1040 is deenergized at the end of the first impulse of the first digit, it steps the wipers of the switch 1042 to their respective first off-normal positions, closes the off-normal springs 1049, closes the off-normal springs 814, and opens the off-normal springs 881. The opening of the springs 881 results in the interruption of the circuit over which dial tone current is applied to the calling line and closure of the springs 814 results in the application of ground to C142 independently of R830. With the springs 1049 closed, a circuit is prepared for energizing M1040 by way of the self-interrupting contacts associated with MA1041. At the end of the first impulse of the first digit, when the operating circuit for R810 is again completed at the impulsive device of the calling subscriber's substation, this relay re-operates preparatory to again energizing M1040. During each impulse of the first digit, R810 restores and then operates, thereby to cause the magnet M1040 to step the wipers of the switch 1042 until they stand in engagement with the respective associated contacts, corresponding to the impulse of the digit dialed. In the present assumed case, wherein the number of the calling line is 220, the first digit will comprise only two impulses so that, at the conclusion thereof, the switch wipers of the rotary switch 1042 stand in their respective second off-normal positions. During such impulsive and due to the slow-to-release characteristics thereof, the relays R830, R840 and R850 remain in their respective operated positions.

Shortly following the end of the first digit dialed at the calling substation A, R840 restores to open, at RA842, the operating circuit for R850 and to interrupt, at RA841, a point in the short-circuiting path for the upper winding of R860. With this short circuit interrupted, the two windings of R860 are energized in series over a circuit extending from ground at the off-normal spring 981 embodied in the rotary switch 974, this circuit extending by way of the off-normal spring 982, C197, RA904, C178, RA864, and through the upper and lower windings of R860 to battery. Upon completing its operation R860 interrupts, at RA861 and RC862, a point in the path, traced previously, for short-circuiting its upper winding and, at RA861 and RC863, prepares a circuit for energizing the upper winding of R870. At RA866 and the associated contact RC867, the relay R860 prepares a circuit for energizing M1000 embodied in the rotary switch 1002 in accordance with the impulses comprising the second digit dialed at the calling subscriber's substation.

At the beginning of the first impulse of the second dialed digit, when R810 again restores, the above-noted operating circuit for M1000 is completed at RA811, this circuit extending from ground at the armature noted by way of RC813, RA833, C182, RA958, C183, the winding of R840, C189, RA866, RC867, RA874, RC876, C187, and through the winding of M1000 to battery. As a consequence of the re-energization of R840, this relay again operates to cause the re-operation of R850 and to complete, at RA841, the above-noted circuit for energizing the upper winding of R870, this circuit extending from ground at the armature noted by way of RA861, RC863 and the upper winding of R870 to battery. The last-mentioned relay, like R860, is constructed to operate in two steps; that is, it operates only RA871 in response to the energization of its upper winding and assumes its fully operated position only when its two windings are energized in series. When RA871 is operated in response to the energization of the upper winding noted, it completes a short-circuiting path for the lower winding of R870, this path extending from ground on RA841 by way of RA861, RC863, the lower winding noted, RA871, C184, RA868 and C205 to ground at RA859.

In view of the preceding description, it will be understood that M1000 is energized and deenergized once during each impulse transmitted from the impulsive device at the calling subscriber's substation. Each time this magnet is energized, it steps the wipers of the switch 1002 one step so that, at the conclusion of the series of impulses comprising the second dialed digit, these wipers stand in engagement with the associated contacts corresponding to the number of impulses of the digit. In the present assumed case, wherein the second numeral of the number identifying the called subscriber's telephone is 2, the second digit will comprise only two impulses so that, at the conclusion of the digit, the switch wipers SW1003 and SW1004 stand in their respective second off-normal positions. When these wipers are caused to take their first step, the off-normal springs 815 and 1005 are closed. The first-mentioned springs function to apply multiple ground to C142, thereby to insure that the finder-connector link illustrated is marked as busy in the bank contacts of the rotary switch 702 embodied in the allotter means illustrated in Fig. 7. With the springs 1005 closed a circuit is prepared for energizing M1000 by way of the self-interrupting contacts associated with MA1001.

At the conclusion of the second digit dialed at the calling subscriber's substation, when R810 is held energized for a time interval sufficient to permit the restoration of R840, the path short-circuiting the upper winding of R870 is interrupted at RA841. As a consequence, the two windings of R870 are energized in series, and this relay assumes its fully operated position. With R869 and R870 operated, a circuit is completed for energizing M1010, this circuit extending from ground at RA865 by way of RA873, C186, SW1004, C221, SW1048, C226, and through the winding of M1010 to battery. When energized over the above-traced circuit, the clutch magnet M1010 attracts its armature MA1011, thereby operatively to associate the control element 1016 with the operating member 1019 so that, when this member is subsequently moved to its right off-normal position by M1030, the contact segments carried by the shaft 1016 will be moved into engagement with the wipers illus-

trated to the right of the element 1016. The relay R870, upon operating, also completes a circuit for energizing the wiper switching relay R860, this circuit extending from ground at RA865 by way of RA873, C186, SW1003, C208, RA866 and through the winding of R960 to battery. Shortly following the operation of R870, the relay R850 restores to complete a circuit for energizing M1030, this circuit extending from ground at RA856 by way of RA872, C185, SW1043, and through the winding of M1030 to battery. When energized, M1030 attracts the armature carried by the operating member 1019 to the right, thereby to bring the contact segments carried by the shaft 1016 into engagement with the wipers or the bank conductors shown to the right of this shaft. This magnet also completes, at MA1031, a holding circuit for itself, this circuit extending from ground at RA907 by way of C204, MA1031 and the winding of M1030 to battery.

The relay R960, upon operating, completes, at RA964, a locking circuit for itself, which circuit extends from ground at RA902 by way of C183, RA964, and through the winding of R960 to battery. At its armatures RA861, RA966 and RA968, this relay associates the link line conductors C182, C185 and C186 with the switch wipers SW978, SW979, and SW980 so that the line testing apparatus is operatively associated with the three lower contact sets terminating the conductors of the lines 211 to 220, inclusive, as extended to these contact sets through the switching unit 1014.

With the finder-connector link in this condition, it is in readiness to respond to impulses comprising the third digit dialed at the calling subscriber's substation. Thus, when the relay R870 operates, it prepares, at RA874 and RC875, a circuit for energizing the motor magnet M970 of the switch 974 in accordance with the impulses of the third digit. This circuit, which is completed when R810 restores at the beginning of the first impulse of the third digit, extends from ground at RA811 by way of RC813, RA835, C182, RA958, C183, the winding of R840, C189, RA866, RC867, RA874, RC875, C179, RC927, RA926, C199 and through the winding of M970 to battery. Since R840 is energized in series with M970, it again operates to cause the operation of R850 and to recomplete the above-traced circuit for short circuiting the lower winding of R870, but this latter relay remains operated due to the continued energization of its upper winding. The relay R850 also completes a holding circuit for R860, these two relays remaining energized during the period of impulses when the impulses are being transmitted to M970. During each impulse of the third digit, M970 is energized and deenergized and operates to drive the wipers of the switch 974 at the rate of one step for each impulse. In the present case, wherein the called line is the tenth line in the selected group of ten lines, the third or final digit dialed at the calling substation will necessarily comprise ten impulses so that, at the conclusion thereof, the switch wipers of the switch 974 stand in their respective tenth off-normal positions. When these wipers are stepped to their respective first off-normal positions, the off-normal spring 981 is moved from engagement with the associated spring 982 and into engagement with the spring 983, thereby to prepare a circuit for causing M970 to restore the wipers of the switch 974 to normal when the connection 75

involving the link is subsequently cleared out. It is noted that the disengagement of the off-normal spring 981 from the spring 982 opens a point in the holding circuit for R860, this relay being held energized, during the period of impulsion, over the alternative holding circuit noted above. With the wipers of the switch 974 operated to their respective tenth off-normal positions, the line conductors C214 and C215 and the test conductor C216 of the line 220 are connected through to the armatures RA961, RA968 and RA966, respectively. The operations which occur following the selection of the called line in the above-described manner depend upon whether this line is found idle or busy.

Operation of a connector switch to select a called line in an odd numbered group of lines

Before describing these operations, however, the operation of the connector switch illustrated, to select a called line included in an odd numbered group of one hundred lines, will be considered. Assume, for example, that the subscriber's line 211 is the calling line and the line 111 is desired by the calling party at the substation C associated with the line 211. In this case, the operations of the finder portion of the link, the allotter means and the connector portion of the link are essentially the same as those described above with the exception, however, that the wipers of the rotary switch 1042 are stepped only one step in response to the single impulse of the first digit dialed at the calling substation. At the end of the first digit, therefore, SW1043 stands in its first off-normal position, or in engagement with the second contact of the contact set associated therewith. With the wiper SW1043 standing in this position, a circuit is prepared for energizing the magnet M1020, rather than the magnet M1030. When the second digit is dialed, the rotary switch 1002 is caused to operate in the exact manner described above. In this case, however, the second digit, like the first, comprises a single impulse so that, at the conclusion of the digit, the switch wipers SW1003 and SW1004 stand in their respective first off-normal positions. With SW1003 in this position, the circuit for the wiper switching relay R960, as traced previously, is held open so that the armatures RA961, RA966 and RA968 embodied in this relay retain the link line conductors associated with the switch wipers SW975, SW976 and SW977 of the switch 974. Shortly following the end of the second digit, the clutch magnet M1010 is energized over the exact circuit described above and shortly following the resulting operation of this magnet, the operating circuit for M1020 is completed, this last-mentioned circuit extending from ground at RA856 by way of RA872, C185, SW1043, and through the winding of M1020 to battery. This magnet, upon being energized actuates the member 1019 to rotate the control element 1016 in a direction to bring the contact segments carried thereby into engagement with the wipers shown to the left of the control element. The operations occurring from this point on are exactly the same as those described above with the exception that the selection of the called line 70 from the selected subgroup of lines is accomplished through the operation of the three upper wipers SW975, SW976 and SW977 of the switch 974, rather than through the three lower wipers SW978, SW979 and SW980, as was the case for 75 the selection of the line 220.

From the immediately preceding description, it will be apparent that the odds and evens group selection is determined by the operation of the two switches 1002 and 1042 in response to the impulses comprising the first and second digits dialed at the calling substation. For example, if a called line is included in an odd numbered group of one hundred lines SW1043 embodied in the switch 1042 is brought to rest in engagement with an associated contact included in the circuit for energizing M1020; whereas, if the called line is included in an even numbered group of one hundred lines, the wiper noted is stopped in engagement with a contact included in the circuit for energizing M1030. This mode of selection determines which of the two twenty line subgroups terminating at each of the switches 1013, 1014, etc., will be selected. In a somewhat similar manner, the position of SW1003 embodied in the rotary switch 1002 at the conclusion of the second digit determines the smaller group of ten lines which will be associated with the link line comprising the conductors C192 and C196. Thus, if the number of impulses transmitted to the switch 1002 is odd, no circuit 2 is completed for energizing the wiper switching relay R960 and the link line is connected to the upper three wipers of the switch 974 to be associated with one small subgroup of ten lines. If, on the other hand, the number of impulses transmitted to the switch 1002 is even, a circuit, traced above, is completed for energizing the wiper switching relay R960 so that the link line noted is associated with the three lower switch wipers SW978, SW979, and SW980, which wipers are, in turn associated with the contact sets to which the lines of the other small subgroup of ten lines are extended. It will be noted that this arrangement permits the so-called decimal system of selection to be employed, since in no case are more than ten impulses required for controlling the successively operating group, subgroup, and units selecting means.

Operation of a connector switch following the selection of an idle called line

Continuing now with the operation of the apparatus to establish a connection between the calling line 111 and the called line 220, it is pointed out that, if this or any other line is busy, this condition is identified by the presence of ground potential on the control conductor associated therewith, whereas, if the line is idle, battery from the cut-off relay associated therewith is present on the associated control conductor.

Assuming the called line 220 to be idle at the time it is selected by the rotary switch 974, a circuit is completed when the relays R840 and R850 restore, shortly following the conclusion of the third series of impulses transmitted to the connector portion of the link, for energizing the ringing relay R950. The two relays R840 and R850, upon restoring also open, at their respective armatures RA841 and RA855, the remaining holding circuits for R860 and R870, causing these latter relays to restore. When the two relays R860 and R870 restore, the operating circuit for M1010 is interrupted at RA865 and RA873. The restoration of R870 also results in the interruption of the original operating circuits for M1030 70 and the wiper switching relay R960, respectively, but as was described above, these two elements are held energized over locking circuits established immediately upon the operation of the respective elements. With M1030 energized, the 75

control element 1016 of the switching unit 1014 is held clutched to the operating member 1019 independently of the condition of M1010, all in the manner set forth in the description with reference to Figs. 1 to 4, inclusive, of the drawings.

As pointed out above, immediately upon the restoration of R850, a circuit is completed for energizing the ringing relay R950, assuming the called line to be idle. This circuit extends from battery on C216 by way of the bank conductor 1034, the contact segment 1027, C212, SW979, RC967, RA966, C195, RA922, RC923, C176, RA851, RC853, C173, the lower winding of R950, RC945, RA944 and C194 to ground at RA903. With its lower winding energized, R950 operates to complete, at RA955, a circuit extending from ground at RA902 for energizing its upper winding, and, with its upper winding energized, it fully operates to connect the line conductors of the called line 220 to the link line conductors C192 and C196. At its armature RA956, the relay R950 applies ground to C195 which is extended by way of the switches 974 and 1012 to the control conductor C216 associated with the called line, thereby to mark this line as busy in the bank conductors of the connector switches embodied in the various other links.

When the link line conductors C192 and C196 are connected to the line conductors C214 and C215 of the called line 220, a circuit is completed for energizing the alternating current signal device, conventionally provided at the substation of the called party B, this circuit starting from one side of the alternating ringing current generator at RC932 and extending by way of RA931, C192, RA954, RA961, RC962, SW978, C211, the contact segment 1025, the bank conductor 1032, C214, the signal device bridged across the line conductors C214 and C215 at the called substation B, C215, the bank conductors 1033, the contact segment 1026, C213, SW980, RC969, RA968, RA957, C196, RA935, RC931 and through the lower winding of R930 to the opposite terminal of the ringing current generator. The relay R930 is so constructed that it does not operate when energized by the alternating ringing current flowing in the above-traced circuit. The operation of R950 also causes ring-back tone current to be applied to the loop extending back to the calling subscriber's substation, the path of this current starting at one side of the ring-back tone source at RC953 and extending by way of RA951, RA938, the condenser 191, and one side of the loop to the receiver at the calling subscriber's substation, through this receiver and back to the grounded side of the ring-back tone source at the grounded terminal of the lower winding of R810. By these operations, the called subscriber is informed that a connection has been established to his telephone and awaits attention, and the calling subscriber is informed that the called subscriber's substation is being rung.

When the called party answers by lifting his receiver from its hook, a circuit is completed for energizing the lower winding of the ring cut-off relay R930, this circuit being identical with that described above for the path of the ringing current, with the exception that a direct current bridge connected across the line conductors C214 and C215 of the called line is substituted for the signal device traversed by the ringing current. When the lower winding of R930 is energized over the circuit noted, it partially operates to complete, at RA934, a circuit extending from

ground at RA902 for energizing its upper winding and, following the energization of the last-mentioned winding, it fully operates to complete, at its armatures RA931 and RA935 and their respective associated contacts RC933 and RC936, a 5 talking connection between the calling and called subscribers' substations. It is to be noted that, when RA931 and RA935 are operated from engagement with their respective associated contacts RC932 and RC937, the path of the ringing 10 current, as traced above, is broken, thereby to discontinue the application of this current to the called subscriber's line. Similarly, the operation of RA938 from engagement with its associated contact discontinues the application of ring-back 15 tone current to the loop extending to the calling subscriber's substation. When the talking loop is completed to the called subscriber's substation, a circuit is completed for energizing R820, this circuit starting from ground at the 20 lower winding of R820 and extending over one side of the loop to the called substation, through the bridge across the line conductors at this substation, back over the opposite side of the loop, and through the upper winding of R820 to battery. The relay R820, upon operating, completes, at RA821, a multiple circuit for holding R908 25 operated independently of the condition of the slow-to-release relay R830. By this arrangement, the connector switch is, in a well-known manner, 30 held operated until such time as the connection is cleared out at both the calling and called substations. With the system in this condition, the calling and called parties may converse as desired, talking battery being supplied to the loop 35 extending to the calling line from the windings of R810 and talking battery being supplied to the loop extending to the called line from the windings of R820.

Operation of a connector switch following the selection of a busy called line

Before describing the release of the connection as established in the above-described manner, it will be assumed that, at the time the called line is selected, it is involved in another previously established connection. In this regard it will be recalled that, at the time the line 220 is selected and for an interval thereafter, the relay R950 remains energized. With the called line busy, therefore, a circuit is completed for energizing the busy relay R940, this circuit extending from ground on the control conductor C216 associated with the called line by way of the bank conductor 1034, the contact segment 1027, C212, SW979, RC967, RA966, C195, RA922, RC923, C176, RA851, RA852, C175, and through the winding of R940 to battery. The busy relay R940, upon operating, prepares, at RA944 and RC946, a holding circuit for itself, which circuit is completed shortly after its operation when R850 restores, and extends from ground at RA903 by way of C194, RA944, RC946, C174, RC954, RA852, C175, and through the winding of R940 to battery. Thus, the busy relay R940 is locked energized until such time as the connection established to the called line is cleared out. At RA944 and RC945, the relay R940, upon operating, opens a point in the circuit for energizing the lower winding of the switching relay R950, thereby to prevent this relay from being energized in the event the previously established connection to the called line is cleared out before the calling party A hangs up to initiate the release of the link as described hereinafter. At its armature RA941 75

and the associated contact RC943, the busy tone relay applies busy tone current to the loop extending to the calling subscriber's substation, the path of this current extending from one side of the busy tone current source at RC943 by way of RA941, RC952, RA951, RA938, the condenser 191, one side of the loop extending to the calling subscriber's substation, through the receiver at this substation, the opposite side of the loop extending to the calling subscriber's substation, back to the grounded side of the busy tone current source at the lower winding terminal of the lower winding of R810.

Release of the link

- 15 Following the receipt of busy tone, the calling party may initiate the release of the finder-connector link illustrated by hanging up his receiver to interrupt the operating circuit for R810. When R810 restores, it interrupts, at RA811, the operating circuit for R830, which latter relay, in turn, restores to open, at RA834, the operating circuit for R900, and to open, at RA833, the holding circuits for R510 and R570, causing these relays to restore. When R570 restores, it opens, at RA574, the holding circuit for M540, which magnet restores MA541 to open a further point in its holding circuit, and releases the operating member 515 so that this member returns to its normal position. When the last-mentioned member is returned to its normal position, the clutch 509 is released so that the control element 507 of the switch 505 is unclutched from the member 515. Thus, the finder switch illustrated in Figs. 5 and 6 is entirely released and in readiness for further use. In this connection, it will be noted that the finder switch is of the non-homing type, that is, the wipers of the various rotary switches included therein are left standing in the positions to which they are operated during the setting up of the connection.
- When R900 restores in the manner described above, it interrupts, at RA903, the holding circuit for the busy relay R940 and, at RA902, the holding circuit for the ringing relay R950, causing these two relays to restore. At its armature RA907, the relay R900, upon restoring, opens the holding circuit for M1030, to permit the operating member 1019 to return to its normal position, at which time the clutch 1018 is released, thereby to release the control element 1016 from operative engagement with the member 1019. When M1030 is deenergized, a further point is opened at MA1031 in the holding circuit for this magnet.
- At RA905, the relay R900, upon restoring, completes a circuit for energizing M970 by way of the self-interrupting contacts associated with MA971, this circuit extending from ground at the off-normal spring 981 by way of the spring 983, C200, MA971, C198, RA905, C199, and through the winding of M970 to battery. The magnet M970 now operates, buzzer fashion, to return the wipers of the rotary switch 974 to their respective normal positions, at which time the off-normal spring 981 is disengaged from the associated spring 983 and returned to its normal position in engagement with the spring 982. There results the deenergization of the magnet M970, with the wipers of the switch 974 standing in their respective normal positions. When the switch 974 is restored to normal, the off-normal springs 816 are opened to remove one of the multiple grounds from C142.
- At RA909, the relay R900, upon restoring, completes a circuit for energizing M1000 embodied in the switch 1002 by way of the self-interrupting

contacts associated with MA1001. This circuit extends from ground, at RA909, by way of C206, the off-normal springs 1005, MA1001 and the winding of M1000 to battery. The magnet M1000, in cooperation with the self-interrupting contacts associated with MA1001, operates to return the wipers of the switch 1002 to their respective home positions, at which time the off-normal springs 1005 are opened to interrupt the circuit for M1000 and the off-normal springs 815 are opened to remove another multiple ground from C142.

At RA909', the relay R900, upon restoring, completes a circuit for energizing M1040, this circuit extending from ground at the armature noted by way of C297, the off-normal springs 1049, MA1041, and the winding of M1040 to battery. The magnet M1040 in cooperation with the self-interrupting contacts associated with MA1041 operates to return the wipers of the switch 1042 to normal, at which time the off-normal springs 1049 are opened to interrupt the above-traced operating circuit for this magnet, and the off-normal springs 814 are opened, thereby completely to remove ground from the conductor C142. Thus, the connector switch illustrated in Figs. 8, 9 and 10 is restored to its normal condition and the finder-connector link embodying the same is marked as idle in the bank contacts of the rotary switch 702 included in the allotter means illustrated in Fig. 7. This last-mentioned operation is accomplished by the removal of ground from C142 in the manner described above.

In the event a talking connection is established between the calling and called substations in the manner set forth above, the release of this connection at the end of the conversation is under the control of the last party to hang up. Thus, if the party at the substation A restores his receiver to its hook, to cause the sequential restoration of R810 and R830, only the finder switch illustrated in Figs. 5 and 6 is released. The release of this switch occurs, in the exact manner pointed out previously, upon the interruption of the holding circuits for R510 and R570 at RA833 of R830. The connector switch illustrated in Figs. 8, 9 and 10 is held operated by the energized relay R820, which relay maintains completed the operating circuit for R900. Thereafter, and when the called party hangs up, R820 restores to cause the restoration of R900, which latter relay, in turn, restores to open, at RA902, the holding circuits for R930, R950 and R960, causing these three relays to restore. When R900 restores, it also completes circuits for energizing the magnets M970, M1000 and M1040 to cause these magnets to operate, buzzer fashion, and return the wipers of the switches in which they are respectively embodied to their respective normal positions, all in the exact manner set forth above. The restoration of R900 also opens the holding circuit for M1030, to cause the release and restoration to normal of the switch 1012. With R900 deenergized and the three rotary switches 974, 1002 and 1042 occupying their normal positions, ground is removed from C142, and the finder-connector link illustrated is marked as idle in the bank contacts of the rotary switch 702 embodied in the allotter illustrated in Fig. 7. Thus, the connection is entirely cleared out and the finder-connector link shown is in readiness for further use.

In the event the called party is the first to hang up, nothing occurs, the entire link being held operated, by virtue of the energized condi-

tion of R830, until such time as the calling party restores his receiver to its hook. The operations resulting when the calling party hangs up are exactly the same as those described above and for that reason are not repeated.

5 **Trunk hunting**

As mentioned in the introductory portion of the specification, each of the connector switches embodied in the various finder-connector links has access to a number of trunk lines outgoing to another exchange or another portion of a larger system, and the arrangement is such that a calling subscriber may, by dialing the predetermined two-digit number 01, cause a connection to be set up by way of an idle one of these trunk lines to the distant exchange. Assume, for example, that the calling subscriber at the substation A desires a connection to a line terminating at the distant exchange rather than a connection to the subscriber's line 220. From the preceding description, it will be recalled that the rotary switch 1042 is responsive to the impulses included in the first series of impulses transmitted from the calling subscriber's substation. Hence, when the digit zero is dialed this switch steps its wipers to their respective tenth off-normal positions. At the conclusion of the digit, when R860 operates, in the exact manner described previously, a circuit is completed for rendering the magnet M1000 responsive to the impulses of the second digit. This second digit, for the purpose of selecting an idle outgoing trunk, comprising a single impulse so that the switch wipers SW1003 and SW1004 are stepped only to their respective first off-normal positions. At the conclusion of the digit, R870 is caused to operate, also in the manner described previously, and this relay, upon operating, completes a circuit for energizing R820, this circuit extending from ground at RA856 by way of RA812, C185, SW1048, C203, and through the winding of R920 to battery. The operation of R870 also completes the previously described circuit for energizing a clutching magnet corresponding to the clutching magnet M1010 and associated with a control element carrying a group of contact segments associated with wipers terminating the group of trunk lines included in the switch 1012, thereby operatively to associate this control element with the operating member 1019.

When R920 operates, it completes, at RA929, a circuit for energizing M1020, this circuit extending from ground at the armature noted by way of C292 and through the winding of M1020 to battery. The magnet M1020, when energized, completes, at MA1021, an obvious holding circuit for itself and attracts the armature carried by the operating member 1019, thereby to actuate the previously mentioned control element and bring the contact segments carried thereby into engagement with the previously mentioned wipers associated therewith and terminating the group of trunk lines.

60 At its armature RA926 and the associated contact RC928, the relay R920 completes a circuit for energizing M970 embodied in the rotary switch 974. This circuit extends from ground at RA809' by way of C181, RA911, RC928, RA926, C198, and through the winding of M970 to battery. The magnet M970 now operates to step the wipers of the switch 974 one step and to complete, at MA971 and MC973, a circuit for energizing R910, this circuit extending from ground at RA824 by way of C209, MAST1, MC973, C201,

RA925, and through the winding of R910 to battery. The relay R910, upon operating, interrupts, at RA811, the previously traced operating circuit for M970, which magnet, in turn, restores MA971 to interrupt, in turn, the operating circuit for R910. This interrelated operation of R910 and M970 continues until such time as the switch wiper SW971 encounters a contact corresponding to an idle trunk outgoing to the distant exchange. The condition of the respective trunk lines, i. e. 10 whether idle or busy, is determined by the potential existing on the control conductor embodied respectively therein. Thus, if any given trunk line is idle, battery potential is present on the associated control conductor, whereas, if the 15 trunk line is busy, ground potential is present on this conductor. As soon as the wipers of the switch 874 are stepped to a position such that SW976 encounters the contact terminating the control conductor associated with an idle trunk 20 line, a circuit is completed for energizing R800, this circuit extending from battery on the control conductor noted by way of SW976, RC967, RA966, C195, RA922, RC924, C177, the lower winding of R800, to ground at RA832. With its lower winding energized, R800 operates to complete, at 25 RA804, a path for short-circuiting its lower winding and for applying ground potential to the control conductor associated with the selected trunk, thereby to mark this trunk as busy in the 30 bank conductors of the other connector switches to which it extends. The path noted extends from ground at RA921 by way of C172, RA831, and RA884 to C177. The relay R800 does not restore when its lower winding is short-circuited, 35 but remains operated by virtue of the energized condition of its upper winding. At its armatures RA801 and RA886 and their respective associated contacts RC803 and RC806, the relay R800 connects the line conductors of the calling line by 40 way of C184 and C171 to the line conductors of the trunk line outgoing to the distant exchange. When this relay operates, it further functions to interrupt, at RA809', the above-traced operating circuit for M970, thereby to stop the interrelated 45 operation of this magnet and R910. At its armature RA802, the relay R800 applies multiple ground to C122, thereby to hold the finder switch operated until such time as the connection established by way of the selected trunk line is 50 cleared out. Similarly, at RA809, the relay R800 applies multiple ground to C180, thereby to hold R900 operated independently of the slow-to-release relay R890.

Immediately upon the operation of R800, the 55 circuit for energizing R810 is interrupted at RA801 and RA805, and the latter relay restores to interrupt, at RA811, the operating circuit for R830, causing the last-mentioned relay to restore. When R830 restores, it interrupts, at 60 RA832, a point in the original circuit over which R800 was energized, but R800 is held energized from ground applied to C177 in the control apparatus associated with the seized outgoing trunk and located at the distant exchange. With R800 65 energized, ground is maintained on C122 at RA808, thereby to hold the finder switch operated, and the operating circuit for R800 is held closed at RA809, thereby to maintain the connector switch operated. With the system in 70 this condition, the connection from the calling line is extended by way of the seized trunk line to the distant exchange and may be further extended through the control apparatus located thereto to the desired subscriber's line. If the 75

distant exchange is automatic in character, the desired connection may be obtained by dialing additional digits for causing the apparatus to set up the connection to the desired line. In this 5 regard, it will be noted that a through metallic circuit is established by way of the conductors C164 and C171 and the conductors of the seized trunk line for transmitting impulses to the control apparatus terminating the trunk line in the 10 distant exchange. If, however, the equipment in the distant exchange is of the manual type, the seizure of the outgoing trunk will cause a signal device to operate at the operator's station and the 15 desired connection is completed in the manner conventionally followed in exchanges of this character.

It will be observed that the release of a connection established by way of one of the outgoing trunks is entirely under the control of the 20 party at the called substation, or of the operator in the distant exchange, assuming this exchange to be of the manual type. Thus, the link illustrated is released only when ground is removed from the control conductor associated with the 25 outgoing trunk, thereby to open the operating circuit for R800. When this occurs, the relay noted restores to remove, at RA808, ground from C122, thereby to initiate the release of the finder switch in the manner described above. Similarly, the operating circuit for R900 is opened 30 at RA809, and when R900 restores, it initiates the release of the connector switch illustrated in Figs. 8, 9, and 10, in the exact manner described above. In the sequence of operations which 35 occurs during the release of a connection of the type noted, R920 is caused to restore, shortly following the restoration of R870. The removal of ground from C142, to mark the finder-connector link illustrated as idle in the bank contacts of the rotary switch 702, occurs when the rotary 40 switches 974, 1002 and 1042 are returned to normal.

While there has been described what is at present considered to be the preferred embodiment 45 of the invention, it will be understood that various modifications may be made therein, and it is contemplated to cover in the appended claims all such modifications as fall within the true spirit and scope of the invention.

50 I claim:

1. In a signaling system, switching apparatus comprising a plurality of switching units each including a control element movable in either of two directions, an operating member for actuating the control elements of said units, each of said control elements normally being non-operatively associated with said member, means individually included in each of said units for operatively associating the corresponding control elements with said member, an operating magnet for actuating said member to move any control element operatively associated therewith in one of said two directions, a second operating magnet for actuating said member to move any control element operatively associated therewith in the other of said two directions, means for selectively energizing said clutch magnets, and means operative only following the energization of one of said clutch magnets for energizing one of said operating magnets.

2. In a signaling system, switching apparatus comprising a plurality of switching units each including a rotatable control element, an operating member for actuating the control elements

of said units, each of said control elements normally being non-operatively associated with said member, means including clutch magnets individually included in each of said units for operatively associating the corresponding control elements with said member, an operating magnet for actuating said member to rotate any control element operatively associated therewith in one direction, a second operating magnet for actuating said member to rotate any control element operatively associated therewith in a direction opposite said first direction, means for selectively energizing said clutch magnets and means operative only following the energization of one of said clutch magnets for energizing one of said operating magnets.

3. In a signaling system, a plurality of lines divided into odd and even numbered groups, a plurality of switching units each having a number of said lines terminating thereat and each including a control element movable in one direction to select a subgroup of lines included in an even numbered group of lines and movable in another direction to select a subgroup of lines included in an odd numbered group of lines, an operating member for actuating the control elements of said units, each of said control elements normally being non-operatively associated with said member, means including clutch magnets individually included in each of said units for operatively associating the corresponding control elements with said member, an operating magnet, corresponding to the odd numbered groups of lines, for actuating said member to move any control element operatively associated therewith in a direction to cause the associated unit to select a subgroup of lines included in an odd numbered group of lines, a second operating magnet, corresponding to the even numbered groups of lines, for actuating said member to move any control element operatively associated therewith in a direction to cause the associated unit to select a subgroup of lines in an even numbered group of lines, means for selectively energizing said clutch magnets, and means operative only following the energization of one of said clutch magnets for energizing one of said operating magnets.

4. In a signaling system, a plurality of lines divided into odd and even numbered groups, a plurality of switching units each having a number of said lines terminating thereat and each including a control element rotatable in one direction to select a sub-group of lines included in an even numbered group and rotatable in the reverse direction to select a subgroup of lines included in an odd numbered group of lines, an operating member for actuating the control elements of said units, each of said control elements normally being non-operatively associated with said member, means including clutch magnets individually included in each of said units for operatively associating the corresponding control elements with said member, an operating magnet, corresponding to the odd numbered groups of lines, for actuating said member to rotate any control element operatively associated therewith in a direction to cause the associated unit to select a subgroup of lines included in an odd numbered group of lines, a second operating magnet, corresponding to the even numbered groups of lines, for actuating said member to rotate any control element operatively associated therewith in a direction to cause the associated unit to select a subgroup of lines in an even numbered group of lines.

lines, means for selectively energizing said clutch magnets, and means operative only following the energization of one of said clutch magnets for energizing one of said operating magnets.

5. In a signaling system, a plurality of lines divided into odd and even numbered groups, a stepping switch including bank contacts arranged in sets, a wiper associated with each of said contact sets and a motor magnet for driving said wipers, a link line extending to said switch, a plurality of switching units each including a control element movable in one direction to connect a subgroup of lines included in an odd numbered group of lines to the bank contacts of said stepping switch and movable in another direction to connect a subgroup of lines included in an even numbered group of lines to the bank contacts of said stepping switch, an operating member for actuating the control elements of said units, each of said control elements normally being non-operatively associated with said member, means including clutch magnets individually included in said units for operatively associating the corresponding control elements with said member, an operating magnet, corresponding to the odd numbered groups of lines, for actuating said member to move any control element operatively associated therewith in a direction to cause the associated unit to connect a subgroup of lines included in an odd numbered group of lines to said bank contacts, a second operating magnet, corresponding to the even numbered groups of lines, for actuating said member to move any control element operatively associated therewith in a direction to cause the associated unit to connect a subgroup of lines included in an even numbered group of lines to said bank contacts, means for selectively energizing said clutch magnets, means operative only following the energization of one of said clutch magnets for energizing one of said operating magnets, means operative following the operation of said last-named means for energizing said motor magnet to cause said stepping switch to select a particular line, and means for connecting said particular line to said link line.

6. In a signaling system, a plurality of lines divided into odd and even numbered groups, a stepping switch including bank contacts arranged in sets, a wiper associated with each of said contact sets and a motor magnet for driving said wipers, a link line extending to said switch, a plurality of switching units each including a control element rotatable in one direction to connect a subgroup of lines included in an odd numbered group of lines to the bank contacts of said stepping switch and rotatable in the reverse direction to connect a subgroup of lines included in an even numbered group of lines to the bank contacts of said stepping switch, an operating member for actuating the control elements of said units, each of said control elements normally being non-operatively associated with said member, means including clutch magnets individually included in said units for operatively associating the corresponding control elements with said member, an operating magnet, corresponding to the odd numbered groups of lines, for actuating said member to move any control element operatively associated therewith in a direction to cause the associated unit to connect a subgroup of lines included in an odd numbered group of lines to said bank contacts, a second operating magnet, corresponding to the even numbered groups of lines, for actuating said member to move any control element operatively associated therewith

in a direction to cause the associated unit to connect a subgroup of lines included in an even numbered group of lines to said bank contacts, means for selectively energizing said clutch magnets, means operative only following the energization of one of said clutch magnets for energizing one of said operating magnets, means operative following the operation of said last-named means for energizing said motor magnet to cause said stepping switch to select a particular line, and means for connecting said particular line to said link line.

7. In a signaling system, a plurality of lines, said lines being divided into odd and even numbered groups, and apparatus for interconnecting said lines for communication thereover, said apparatus comprising a line selecting switch including, in combination, means for simultaneously selecting an odd numbered group of lines and an even numbered group of lines one of which includes a particular line, means partially controlled in accordance with the odd or even number identifying the group of lines including the particular line for selecting the one of said selected odd and even numbered groups of lines which includes said particular line and for simultaneously selecting a subgroup in the selected group, said subgroup including said particular line, and means for selecting said particular line from said selected subgroup of lines. 15 20 25 30

8. In a telephone system, a plurality of lines, said lines being divided into groups, at least a portion of said lines having subscribers' substations individually associated therewith, an impulsive device at each of said substations, a plurality of finder-connector links for interconnecting said lines for communication thereover, and allotter means for assigning said links to successive calling lines in a definite order, each of said links comprising, in combination; means responsive to the initiation of a call on one of said lines for selecting two of said groups of lines one of which includes the calling line, means for selecting the one of said two selected groups of lines which includes the calling line, and for simultaneously selecting a subgroup of lines in said one group of lines, said subgroup including the calling line, means for selecting the calling line from said selected subgroup of lines and for conditioning the connector portion of the link to be responsive to impulses transmitted from the impulsive device included in the substation associated with the calling line, means responsive to one series of impulses transmitted from said last-mentioned impulsive device for selecting a group of lines including a called line, means responsive to a second series of impulses for selecting a subgroup of lines included in said selected group, said subgroup including the called line, means responsive to a third series of impulses for selecting the called line from said subgroup, and means for establishing a connection between said calling and called lines in the event the called line is idle.

9. In a telephone system, a plurality of lines, 65
said lines being divided into groups, at least a portion of said lines having subscribers' substations individually associated therewith, an impulsive device at each of said substations, a plurality of finder-connector links for interconnecting said lines for communication thereover, and allotted means for assigning said links to successive calling lines in a definite order, each of said links comprising, in combination, means responsive to the initiation of a call on one 75

- of said lines for selecting two of said groups of lines one of which includes the calling line, means for selecting the one of said two selected groups of lines which includes the calling line, and for simultaneously selecting a subgroup of lines in said one group of lines, said subgroup including the calling line, means for selecting the calling line from said selected subgroup of lines and for conditioning the connector portion of the link to be responsive to impulses transmitted from the impulsive device included in the substation associated with the calling line, means responsive to one series of impulses transmitted from said last-mentioned impulsive device for selecting a group of lines including a called line, means responsive to a second series of impulses for selecting a subgroup of lines included in said selected group, said subgroup including the called line, means responsive to a third series of impulses for selecting the called line from said subgroup, means for testing said called line to determine its idle or busy condition, means for establishing a connection between said calling and called lines in the event the called line is idle, and means for applying busy tone current to the calling line in the event said called line is busy.

10. In a telephone system, a plurality of lines, said lines being divided into odd and even numbered groups, at least a portion of said lines having subscribers' substations individually associated therewith, an impulsive device at each of said substations, a plurality of finder-connector links for interconnecting said lines for communication thereover, and allotter means for assigning said links to successive calling lines in a definite order, each of said links comprising, in combination; means responsive to the initiation of a call on one of said lines for selecting an odd numbered group of lines and an even numbered group of lines, one of which includes the calling line, means for selecting the one of said two selected groups of lines which includes the calling line and for simultaneously selecting a subgroup of lines in said one group of lines, said selected subgroup including the calling line, means for selecting the calling line from said selected subgroup and for conditioning the connector portion of the link to be responsive to impulses transmitted from the impulsive device included in the substation associated with the calling line, means responsive to one series of impulses transmitted from said last-mentioned impulsive device for selecting an odd numbered group of lines or an even numbered group of lines depending upon the number of impulses in the series, the selected one of said groups of lines including a called line, means responsive to a second series of impulses transmitted from said impulsive device for selecting a subgroup of lines in said selected group of lines, said subgroup including the called line, means responsive to a third series of impulses for selecting the called line from said selected subgroup, and means for establishing a connection between said calling and called lines in the event the called line is idle.

11. In a telephone system, a plurality of lines, said lines being divided into odd and even numbered groups, at least a portion of said lines having subscribers' substations individually associated therewith, an impulsive device at each of said substations, a plurality of finder-connector links for interconnecting said lines for communication thereover, and allotter means for assigning said links to successive calling lines in a definite order, each of said links comprising,

5 10 15 20 25 30 35 40 45 50 55 60 65 70 75 80 85 90 95 100 105 110 115 120 125 130 135 140 145 150 155 160 165 170 175 180 185 190 195 200 205 210 215 220 225 230 235 240 245 250 255 260 265 270 275 280 285 290 295 300 305 310 315 320 325 330 335 340 345 350 355 360 365 370 375 380 385 390 395 400 405 410 415 420 425 430 435 440 445 450 455 460 465 470 475 480 485 490 495 500 505 510 515 520 525 530 535 540 545 550 555 560 565 570 575 580 585 590 595 600 605 610 615 620 625 630 635 640 645 650 655 660 665 670 675 680 685 690 695 700 705 710 715 720 725 730 735 740 745 750 755 760 765 770 775 780 785 790 795 800 805 810 815 820 825 830 835 840 845 850 855 860 865 870 875 880 885 890 895 900 905 910 915 920

one series of impulses transmitted thereto for selecting a group of said units to which extend an odd numbered group of lines and an even numbered group of lines, one of which includes a called line, and for determining the direction of movement of the control elements included in the selected units in accordance with the odd or even number identifying the group of lines including the called line, means responsive to a second series of impulses for selecting the one of said last-mentioned selected group of units to which the called line extends, means operative following the operation of said last-named means for moving the control element of the selected unit in the determining direction, means responsive to a third series of impulses for selecting the called line from the selected subgroup of lines, and means for establishing a connection between the calling and called lines in the event the called line is idle.

13. In a telephone system, a plurality of lines, said lines being divided into odd and even numbered groups, at least a portion of said lines having subscribers' substations individually associated therewith, an impulsive device at each of said substations, a plurality of finder-connector links for interconnecting said lines for communication thereover, and allotter means for assigning said links to successive calling lines in a definite order; the finder and connector portions of each link comprising a plurality of switching units each having a number of said lines terminating thereat, each of said units including a control element rotatable in one direction to select a subgroup of lines included in an odd numbered group of lines and rotatable in the reverse direction to select a subgroup of lines included in an even numbered group of lines; the finder portion of each link further comprising means responsive to the initiation of a call on one of said lines for selecting a group of said units to which extend an odd numbered group of lines and an even numbered group of lines one of which includes the calling line, means operative following the operation of said last-mentioned means for selecting from the selected group of units the unit to which the calling line extends and for determining the direction of movement of the control element of the selected unit in accordance with the odd or even number identifying the group of lines including the calling line, means for rotating the control element of the selected unit in the direction determined by said last-mentioned means, and means for selecting the calling line from the selected subgroup of lines and for conditioning the connector portion of the link to be responsive to impulses transmitted from the impulsive device included in the substation associated with the calling line; and the connector portion of each link further comprising means responsive to one series of impulses transmitted thereto for selecting a group of said units to which extend an odd numbered group of lines and an even numbered group of lines, one of which includes a called line, and for determining the direction of movement of the control elements included in the selected units in accordance with the odd or even number identifying the group of lines including the called line, means responsive to a second series of impulses for selecting the one of said last-mentioned selected group of units to which the called line extends, means operative following the operation of said last-named means for rotating the control element of the selected unit in the determined direction, means responsive to a third series of impulses for selecting the called line from the selected subgroup of lines, means for testing the called line to determine its idle or busy condition, means for establishing a connection between the calling and called lines in the event the called line is idle, and means for applying busy tone current to the calling line in the event the called line is busy.

14. In a telephone system, a plurality of lines divided into odd and even numbered groups, at least a portion of said lines having subscribers' substations individually associated therewith, an impulsive device at each of said substations, a plurality of finder-connector links for interconnecting said lines for communication thereover, and allotter means for assigning said links to successive calling lines in a definite order; the finder and connector portions of each link comprising a plurality of switching units each having a number of said lines terminating thereat, each of said units including a control element rotatable in one direction to select a subgroup of lines included in an odd numbered group of lines and rotatable in the reverse direction to select a subgroup of lines included in an even numbered group of lines; the finder portion of each link further comprising means responsive to the initiation of a call on one of said lines for selecting a group of said units to which extend an odd numbered group of lines and an even numbered group of lines one of which includes the calling line, means operative following the operation of said last-mentioned means for selecting from the selected group of units the unit to which the calling line extends and for determining the direction of movement of the control element of the selected unit in accordance with the odd or even number identifying the group of lines including the calling line, means for rotating the control element of the selected unit in the direction determined by said last-mentioned means, and means for selecting the calling line from the selected subgroup of lines and for conditioning the connector portion of the link to be responsive to impulses transmitted from the impulsive device included in the substation associated with the calling line; and the connector portion of each link further comprising means responsive to one series of impulses transmitted thereto for selecting a group of said units to which extend an odd numbered group of lines and an even numbered group of lines, one of which includes a called line, and for determining the direction of movement of the control elements included in the selected units in accordance with the odd or even number identifying the group of lines including the called line, means responsive to a second series of impulses for selecting the one of said last-mentioned selected group of units to which the called line extends, means operative following the operation of said last-named means for rotating the control element of the selected unit in the determined direction, means responsive to a third series of impulses for selecting the called line from the selected subgroup of lines, means for testing the called line to determine its idle or busy condition, means for establishing a connection between the calling and called lines in the event the called line is idle, and means for applying busy tone current to the calling line in the event the called line is busy.

15. In a telephone system, a plurality of lines divided into groups, each of said groups of lines being identified by an odd or an even number, and finder means having access to said lines, said finder means comprising, in combination; means responsive to the initiation of a call on one of said lines for selecting two groups of said lines one of which includes the calling line, 75

means operative following the operation of said last-named means and partially controlled in accordance with the odd or even number identifying the group of lines including the calling line 5 for selecting the one of said selected groups which includes the calling line and for simultaneously selecting a subgroup included in said one group of lines, said subgroup including said calling line, and means for selecting said calling line

10 from said selected subgroup of lines.

16. In a telephone system, a plurality of lines divided into groups, and finder means having access to said lines, said finder means comprising, in combination; a plurality of switching units each 15 having two subgroups of said plurality of lines terminating thereat, one subgroup of lines terminating at each unit being included in one group of lines and the other subgroup of lines terminating thereat being included in another group 20 of lines, each of said units including a control element movable in one direction to cause the unit to select one of the subgroups of lines extending thereto and in another direction to cause the unit to select the other subgroup of lines 25 extending thereto, and means responsive to the initiation of a call on one of said lines for causing the control element of the unit at which the calling line terminates to be moved in a direction to select the subgroup of lines including said 30 calling line.

17. In a telephone system, a plurality of lines divided into groups, and finder means having access to said lines, said finder means comprising, in combination; a plurality of switching units 35 each having two subgroups of said plurality of lines terminating thereat, one subgroup of lines terminating at each unit being included in one group of lines and the other subgroup of lines terminating thereat being included in another group 40 of lines, each of said units including a control element rotatable in one direction to cause the unit to select one of the subgroups of lines extending thereto and rotatable in the reverse direction to cause the unit to select the other subgroup of lines extending thereto, and means 45 responsive to the initiation of a call on one of said lines for causing the control element of the unit at which the calling line terminates to be rotated in a direction to select the subgroup of 50 lines including said calling line.

18. In a telephone system, a plurality of lines divided into odd and even numbered groups, and finder means having access to said lines, said finder means comprising, in combination; a plurality of switching units each having a number 55 of said lines terminating thereat and each including a control element movable in one direction to select a subgroup of lines included in an odd numbered group of lines and movable in another direction to select a subgroup of lines included in an even numbered group of lines, means responsive to the initiation of a call on one of said lines for selecting a group of said units to which extend an odd numbered group 60 of lines and an even numbered group of lines one of which includes the calling line, means operative following the operation of said last-mentioned means for selecting from the selected group of units the unit to which the calling line 65 extends and for determining the direction of movement of the control element of the selected unit in accordance with the odd or even number identifying the group of lines including the calling line, means for moving the control element 70 of the selected unit in the direction determined

by said last-mentioned means, and means for selecting the calling line from the selected subgroup of lines.

19. In a telephone system, a plurality of lines divided into odd and even numbered groups, and finder means having access to said lines, said finder means comprising, in combination; a plurality of switching units each having a number of lines terminating thereat and each including a control element rotatable in one direction to 1 select a subgroup of lines included in an odd numbered group of lines and rotatable in the opposite direction to select a subgroup of lines included in an even numbered group of lines, means responsive to the initiation of a call on 1 one of said lines for selecting a group of switching units to which extend an odd numbered group of lines and an even numbered group of lines one of which includes the calling line, means operative following the operation of said last-mentioned means for selecting from the selected group of units the unit to which the calling line extends and for determining the direction of rotation of the control element of the selected unit in accordance with the odd or even number 2 identifying the group of lines including the calling line, means for rotating the control element of the selected unit in the direction determined by said last-mentioned means, and means for selecting the calling line from the selected sub- 30 group of lines.

20. In a telephone system, a plurality of lines divided into odd and even numbered groups, and finder means having access to said lines, said finder means comprising, in combination; a plurality of switching units each having a number 35 of said lines terminating thereat and each including a control element movable in one direction to select a subgroup of lines included in an odd numbered group of lines and movable in another direction to select a subgroup of lines included in an even numbered group of lines, means including a pair of magnets for moving said control elements in either of said two directions, normally incomplete operating circuits for said magnets, means responsive to the initiation of a call on one of said lines for selecting a group 40 of said units to which extend an odd numbered group of lines and an even numbered group of lines one of which includes the calling line, means 45 operative following the operation of said last-mentioned means for selecting from the selected group of units the unit to which the calling line extends and for determining, in accordance with the odd or even number identifying the group of lines including the calling line, the one of said magnets to be energized, means operative following the operation of said last-mentioned means for completing the energizing circuit for said one magnet, and means for selecting the calling 50 line from the selected subgroup of lines.

21. In a telephone system, a plurality of lines divided into odd and even numbered groups, and finder means having access to said lines, said finder means comprising, in combination; a plurality of switching units each having a number of said lines terminating thereat and each including a control element rotatable in one direction to select a subgroup of lines included in an odd numbered group of lines and rotatable in 70 the reverse direction to select a subgroup of lines included in an even numbered group of lines, means including a pair of magnets for rotating said control elements in either of said two directions, normally incomplete operating circuits for 75

said magnets, means responsive to the initiation of a call on one of said lines for selecting a group of said units to which extend an odd numbered group of lines and an even numbered group of lines one of which includes the calling line, means operative following the operation of said last-mentioned means for selecting from the selected group of units the unit to which the calling line extends and for determining, in accordance with the odd or even number identifying the group of lines including the calling line, the one of said magnets to be energized, means operative following the operation of said last-mentioned means for completing the energizing circuit for said one magnet, and means for selecting the calling line from the selected subgroup of lines.

22. In a telephone system, a plurality of lines divided into odd and even numbered groups, and finder means having access to said lines, said finder means comprising, in combination; a plurality of switching units each having a number of said lines terminating thereat and each including a control element movable in one direction to select a subgroup of lines included in an odd numbered group of lines and movable in another direction to select a subgroup of lines included in an even numbered group of lines, an operating member common to said units, the control elements individual to said units normally being non-operatively associated with said member, clutching means included in each unit and including a clutch magnet for operatively associating the control element of the corresponding unit with said operating member, operating circuits for said magnets, a first operating magnet, corresponding to the odd numbered groups of lines, for actuating said member to move any control element operatively associated therewith in one of said directions of movement, a second operating magnet, corresponding to the even numbered groups of lines, for actuating said member to move any control element operatively associated therewith in the other of said directions of movement, operating circuits for said operating magnets, means responsive to the initiation of a call on one of said lines for selecting a group of said units to which extend an odd numbered group of lines and an even numbered group of lines, one of which includes the calling line, and for preparing the operating circuits for the clutch magnets individually included in the units of the selected group, means operative following the operation of said last-named means for selecting from the selected group of units the unit to which the calling line extends and for further preparing the operating circuit for the clutch magnet included in the selected unit, means operative following the operation of said last-mentioned means for completing the operating circuit of the clutch magnet included in said selected unit, means responsive to the operation of said last-mentioned means for completing the operating circuit to the one of said first and second magnets which corresponds to the odd or even number of the group of lines including the calling line, and means for selecting the calling line from the selected subgroup of lines.

23. In a telephone system, a plurality of lines divided into odd and even numbered groups, and finder means having access to said lines, said finder means comprising, in combination; a plurality of switching units each having a number of said lines terminating thereat and each including a control element rotatable in one direction to select a subgroup of lines included in

an odd numbered group of lines and rotatable in the opposite direction to select a subgroup of lines included in an even numbered group of lines, an operating member common to said units, the control elements individual to said units normally being non-operatively associated with said member, clutching means included in each unit and including a clutch magnet for operatively associating the control element of the corresponding unit with said operating member, operating circuits for said magnets, a first operating magnet, corresponding to the odd numbered groups of lines, for actuating said member to move any control element operatively associated therewith in one of said directions of rotation, a second operating magnet, corresponding to the even numbered groups of lines, for actuating said member to rotate any control element operatively associated therewith in the other of said directions of rotation, operating circuits for said first and second magnets, means responsive to the initiation of a call on one of said lines for selecting a group of said units to which extend an odd numbered group of lines and an even numbered group of lines, one of which includes the calling line, and for preparing the operating circuits for the clutch magnets individually included in the units of the selected group, means operative following the operation of said last-mentioned means for selecting from the selected group of units the unit to which the calling line extends and for further preparing the operating circuit for the clutch magnet included in the selected unit, means operative following the operation of said last-mentioned means for completing the operating circuit of the clutch magnet included in said selected unit, means responsive to the operation of said last-mentioned means for completing the operating circuit to the one of said first and second magnets which corresponds to the odd or even number of the group of lines including the calling line, and means for selecting the calling line from the selected subgroup of lines.

24. In a telephone system, a plurality of lines divided into odd and even numbered groups, and finder means having access to said lines, said finder means comprising, in combination; a plurality of switching units each having a number of said lines terminating thereat and each including a control element movable in one direction to select a subgroup of lines included in an odd numbered group of lines and movable in another direction to select a subgroup of lines included in an even numbered group of lines, an operating member common to said units, the control elements individual to said units normally being non-operatively associated with said member, clutching means included in each unit and including a clutch magnet for operatively associating the control element of the corresponding unit with said operating member, operating circuits for said magnets, a first operating magnet, corresponding to the odd numbered groups of lines, for actuating said member to move any control element operatively associated therewith in one of said directions of movement, a second operating magnet, corresponding to the even numbered groups of lines, for actuating said member to move any control element operatively associated therewith in the other of said directions of movement, operating circuits for said first and second magnets, means responsive to the initiation of a call on one of said lines for selecting a group of units to which extend an

- odd numbered group of lines and an even numbered group of lines, one of which includes the calling line, and for preparing the operating circuits for the clutch magnets individually included
- 5 in the units of the selected group, means operative following the operation of said last-mentioned means for selecting from the selected group of units the unit to which the calling line extends and for further preparing the operating circuit
- 10 for the clutch magnet of the selected unit, a pair of relays, one of said relays corresponding to the odd numbered groups of lines and including contacts for preparing the operating circuit for said first magnet, the other of said relays correspond-
- 15 ing to the even numbered groups of lines and including contacts for preparing the operating circuit for said second magnet, each of said relays including contacts for completing the operating circuit for the clutching magnet of any
- 20 selected unit, said last-mentioned means being operative to cause the operation of the one of said relays corresponding to the odd or even number identifying the group of lines including the calling line, means controlled by and operable shortly
- 25 following the operation of said last-mentioned relay for completing the operating circuit of the corresponding operating magnet, and means for selecting the calling line from the selected subgroup of lines.
- 30 25. In a telephone system, a plurality of lines divided into odd and even numbered groups, and finder means having access to said lines, said finder means comprising in combination; a plurality of switching units each having a number
- 35 of said lines terminating thereat and each including a control element movable in one direction to select a subgroup of lines included in an odd numbered group of lines and movable in another direction to select a subgroup of lines included in an even numbered group of lines, an operating member common to said units, the control elements individually included in said units normally being non-operatively associated with said member, clutching means included in each
- 40 unit and including a clutch magnet for operatively associating the control element of the corresponding unit with said operating member, operating circuits for said magnets, a first operating magnet, corresponding to the odd numbered groups of lines, for actuating said member to move any control element operatively associated therewith in one of said directions of movement, a second operating magnet, corresponding to the even numbered groups of lines, for actuating said
- 45 member to move any control element operatively associated therewith in the other of said directions of movement, operating circuits for said first and second magnets, means responsive to the initiation of a call on one of said lines for selecting a group of said
- 50 groups of lines, for actuating said member to move any control element operatively associated therewith in one of said directions of movement, a second operating magnet, corresponding to the even numbered groups of lines, for actuating said
- 55 member to move any control element operatively associated therewith in the other of said directions of movement, operating circuits for said first and second magnets, means responsive to the initiation of a call on one of said lines for selecting a group of units to which extend an odd numbered group of lines and an even numbered group of lines, one of which includes the calling line, and for preparing the operating circuits for the clutch magnets individually included in the
- 60 units of the selected group, means operative following the operation of said last-mentioned means for selecting from the selected group of units the unit to which the calling line extends and for further preparing the operating circuit
- 65 for the clutch magnet of the selected unit, a pair of relays, one of said relays corresponding to the odd numbered groups of lines and including contacts for preparing the operating circuit for said first magnet, the other of said relays corre-
- 70 sponding to the even numbered groups of lines
- 75 and including contacts for preparing the operating circuit for said second magnet, each of said relays including contacts for completing the operating circuit for the clutching magnet of any selected unit, said last-mentioned means being operative to cause the operation of the one of said relays corresponding to the odd or even number identifying the group of lines including the calling line, a third relay having a slow-operating characteristic, an operating circuit for said third relay adapted to be completed in response to the operation of either of said pair of relays, and means for selecting the calling line from the selected subgroup of lines.
26. In a telephone system, a plurality of lines divided into odd and even numbered groups, and finder means having access to said lines, said finder means comprising, in combination; a plurality of switching units each having a number of said lines terminating thereat and each including a control element movable in one direction to select a subgroup of lines included in an odd numbered group of lines and movable in another direction to select a subgroup of lines included in an even numbered group of lines, an operating member common to said units, the control elements individually included in said units normally being non-operatively associated with said member, clutching means included in each unit and including a clutch magnet for operatively associating the control element of the corresponding unit with said operating member, operating circuits for said magnets, a first operating magnet, corresponding to the odd numbered groups of lines, for actuating said member to move any control element operatively associated therewith in one of said directions of movement, a second operating magnet, corresponding to the even numbered groups of lines, for actuating said member to move any control element operatively associated therewith in the other of said directions of movement, operating circuits for said operating magnets, a first stepping switch including means responsive to the initiation of a call on one of said lines for selecting a group of said lines and an odd numbered group of lines, one of which includes the calling line, and for preparing the operating circuits for the clutch magnets individually included in the units of the selected group, a second stepping switch including means operative following the operation of said first stepping switch for selecting from the selected group of units the unit to which the calling line extends and for further preparing the operating circuit for the clutch magnet of the selected unit, means controlled jointly by said first and second stepping switches for completing the operating circuit of the last-mentioned clutch magnet and for subsequently completing the operating circuit of the one of said operating magnets corresponding to the odd or even number identifying the group of lines including the calling line, and means for selecting the calling line from the selected subgroup of lines.
27. In a telephone system, a plurality of lines divided into odd and even numbered groups, and finder means having access to said lines, said finder means comprising, in combination; a plurality of switching units each having a number of said lines terminating thereat and each including a control element movable in one direction to select a subgroup of lines included in an odd numbered group of lines and movable in another direction to select a subgroup of lines included in an even numbered group of lines, an operating member common to said units, the control elements individually included in said units normally being non-operatively associated with said member, clutching means included in each unit and including a clutch magnet for operatively associating the control element of the corresponding unit with said operating member, operating circuits for said magnets, a first operating magnet, corresponding to the odd numbered groups of lines, for actuating said member to move any control element operatively associated therewith in one of said directions of movement, a second operating magnet, corresponding to the even numbered groups of lines, for actuating said member to move any control element operatively associated therewith in the other of said directions of movement, operating circuits for said operating magnets, a first stepping switch including means responsive to the initiation of a call on one of said lines for selecting a group of said lines and an odd numbered group of lines, one of which includes the calling line, and for preparing the operating circuits for the clutch magnets individually included in the units of the selected group, a second stepping switch including means operative following the operation of said first stepping switch for selecting from the selected group of units the unit to which the calling line extends and for further preparing the operating circuit for the clutch magnet of the selected unit, means controlled jointly by said first and second stepping switches for completing the operating circuit of the last-mentioned clutch magnet and for subsequently completing the operating circuit of the one of said operating magnets corresponding to the odd or even number identifying the group of lines including the calling line, and means for selecting the calling line from the selected subgroup of lines.

another direction to select a subgroup of lines included in an even numbered group of lines, an operating member common to said units, the control elements individually included in said units normally being non-operatively associated with said member, clutching means included in each unit and including a clutch magnet for operatively associating the control element of the corresponding unit with said operating member, operating circuits for said magnets, a first operating magnet, corresponding to the odd numbered groups of lines, for actuating said member to move any control element operatively associated therewith in one of said directions of movement, a second operating magnet, corresponding to the even numbered groups of lines, for actuating said member to move any control element operatively associated therewith in the other of said directions of movement, operating circuits for said operating magnets, a first stepping switch including means responsive to the initiation of a call on one of said lines for selecting a group of said units to which extend an odd numbered group of lines and an even numbered group of lines, one of which includes the calling line, and for preparing the operating circuits for the clutch magnets individually included in the units of the selected group, a second stepping switch including means operative following the operation of said first stepping switch for selecting from the selected group of units the unit to which the calling line extends and for further preparing the operating circuit for the clutch magnet of the selected unit, means controlled jointly by said first and second stepping switches for completing the operating circuit of the last-mentioned clutch magnet and for subsequently completing the operating circuit of the one of said operating magnets corresponding to the odd or even number identifying the group of lines including the calling line, a third stepping switch including bank contacts adapted to terminate any subgroup of lines included in said plurality of lines when the control element of the unit terminating the subgroup of lines is moved in a direction to select the subgroup, and means whereby said third stepping switch operates to test the lines of a selected subgroup in pairs until the calling line included in the subgroup is found.

28. In a telephone system, finder means comprising a stepping switch including bank contacts arranged in sets, a wiper associated with each of said contact sets and means including a motor magnet for driving said wipers, an operating circuit for said magnet, lines terminating at said contacts and including test conductors, said lines being divided into two small groups with the test conductors of the lines of each group terminating at different sets of said contacts, whereby the lines terminating at said contacts may be tested in pairs during operation of said switch, a relay corresponding to each of said small groups of lines, an operating circuit for each of said relays adapted to be completed by way of the wiper associated with the set of contacts terminating the test conductors of the lines in the group corresponding to the associated relay, and means responsive to the operation of either of said relays for interrupting the operating circuit for said magnet.

29. In a telephone system, finder means comprising a stepping switch including bank contacts arranged in sets, a wiper associated with each of said contact sets and means including a motor magnet for driving said wipers, an operating

circuit for said magnet, a link line extending to said switch, a plurality of lines terminating at said bank contacts and including test conductors, said lines being divided into two small groups with the test conductors of the lines of each group terminating at different sets of said contacts, whereby the lines terminating at said contacts may be tested in pairs during operation of said switch, a relay corresponding to each of said small groups of lines, an operating circuit for each of said relays adapted to be completed by way of the wiper associated with the set of contacts terminating the test conductors of the lines in the group corresponding to the associated relay, and means responsive to the operation of either of said relays for interrupting the operating circuit for said magnet and for connecting a selected line in the group corresponding to the operated relay to said link line.

30. In a telephone system, a plurality of lines, and finder means having access to said lines, said finder means including a plurality of stepping switches each comprising wipers and a motor magnet, an operating circuit for each of said magnets, a relay, an operating circuit for said relay, and control means for successively interconnecting said relay by way of said circuits with different ones of said magnets to cause the successive operation of said switches, said relay, when energized and interconnected with one of said magnets, including contacts interrupting the operating circuit of said one magnet, and each of said magnets, when energized and interconnected with said relay, including contacts interrupting the operating circuit of said relay.

31. In a telephone system, a plurality of lines, and finder means having access to said lines, said finder means including a pair of stepping switches each comprising wipers and a motor magnet, an operating circuit for each of said magnets, a first relay, an operating circuit for said relay, means responsive to the initiation of a call on one of said lines for interconnecting said relay with one of said magnets to cause the switch including said one magnet to operate to a position corresponding to a group of lines including the calling line, said first relay when energized and interconnected with said one magnet including contacts interrupting the operating circuit of said one magnet and said one magnet, when energized, including contacts interrupting the operating circuit of said relay, a second relay operative in response to the operation of the switch including said one magnet to said predetermined position for interconnecting said first relay with the second of said magnets, said first relay, when energized and interconnected with said second magnet, including contacts interrupting the circuit of said second magnet and said second magnet, when energized, including contacts interrupting the operating circuit of said first relay.

32. In a telephone system, a plurality of lines divided into odd and even numbered groups, and line selecting means having access to said lines, said selecting means comprising, in combination, a plurality of switching units each having a number of said lines terminating thereat and each including a control element movable in one direction to select a subgroup of lines included in an odd numbered group of lines and movable in another direction to select a subgroup of lines included in an even numbered group of lines, means responsive to a series of received impulses for selecting a group of said units to which extend an

- odd numbered group of lines and an even numbered group of lines, one of which includes a desired line, and for determining the direction of movement of the control elements respectively embodied in the units of said selected group in accordance with the odd or even number identifying the group of lines including the desired line, means responsive to a second series of received impulses for selecting the one of said group of units to which the desired line extends, means operative following the operation of said last-mentioned means for moving the control element of the selected unit in the direction determined by said first-mentioned means, and means for selecting the desired line from the selected subgroup of lines.
33. In a telephone system, a plurality of lines divided into odd and even numbered groups, and line selecting means having access to said lines, said selecting means comprising, in combination; a plurality of switching units each having a number of said lines terminating thereat and each including a control element rotatable in one direction to select a subgroup of lines included in an odd numbered group of lines and rotatable in the reverse direction to select a subgroup of lines included in an even numbered group of lines, means responsive to a series of received impulses for selecting a group of said units to which extend an odd numbered group of lines and an even numbered group of lines, one of which includes a desired line, and for determining the direction of rotation of the control elements respectively embodied in the units of said selected group in accordance with the odd or even number identifying the group of lines including the desired line, means responsive to a second series of received impulses for selecting the one of said group of units to which the desired line extends, means operative following the operation of said last-mentioned means for rotating the control element of the selected unit in the direction determined by said first-mentioned means, and means for selecting the desired line from the selected subgroup of lines.
34. In a telephone system, a plurality of lines divided into odd and even numbered groups, and line selecting means having access to said lines, said selecting means comprising, in combination; a plurality of switching units each having a number of said lines terminating thereat and each including a control element rotatable in one direction to select a subgroup of lines included in an odd numbered group of lines and rotatable in the reverse direction to select a subgroup of lines included in an even numbered group of lines, means responsive to a series of received impulses for selecting a group of said units to which extend an odd numbered group of lines and an even numbered group of lines, one of which includes a desired line and for determining the direction of movement of the control elements respectively embodied in the units of said selected group in accordance with the odd or even number identifying the group of lines including the desired line, means responsive to a second series of received impulses for selecting the one of said group of units to which the desired line extends, means operative following the operation of said last-mentioned means for rotating the control element of the selected unit in the direction determined by said first-mentioned means, and means responsive to a third series of received impulses for selecting the desired line from the selected subgroup of lines.

35. In a telephone system, a plurality of lines divided into odd and even numbered groups, and line selecting means having access to said lines, said selecting means comprising, in combination; a plurality of switching units each having a number of said lines terminating thereat and each including a control element movable in one direction to select a subgroup of lines included in an odd numbered group of lines and movable in another direction to select a subgroup of lines included in an even numbered group of lines, means including a pair of magnets for moving said control elements in said two directions, operating circuits for said magnets, means responsive to a series of received impulses for selecting a group of said units to which extend an odd numbered group of lines and an even numbered group of lines, one of which includes a desired line, and for determining, in accordance with the odd or even number identifying the group of lines including the desired line, the one of said magnets to be energized, means responsive to a second series of received impulses for selecting the one of said group of units to which the desired line extends, means operative following the operation of said last-mentioned means for completing the operating circuit for said one magnet, and means responsive to a third series of received impulses for selecting the desired line from the selected subgroup of lines.
36. In a telephone system, a plurality of lines divided into odd and even numbered groups, and line selecting means having access to said lines, said selecting means comprising, in combination; a plurality of switching units each having a number of said lines terminating thereat and each including a control element movable in one direction to select a subgroup of lines included in an odd numbered group of lines and movable in another direction to select a subgroup of lines included in an even numbered group of lines, an operating member common to said units, the control elements individually included in said units normally being non-operatively associated with said member, clutching means included in each unit and including a clutch magnet for operatively associating the control element of the corresponding unit with said operating member, operating circuits for said magnets, a first operating magnet, corresponding to the odd numbered groups of lines, for actuating said member to move any control element operatively associated therewith in one of said directions of movement, a second operating magnet, corresponding to the even numbered groups of lines, for actuating said member to move any control element operatively associated therewith in the other of said directions of movement, operating circuits for said first and second magnets, means responsive to a series of received impulses for selecting a group of said units to which extend an odd numbered group of lines and an even numbered group of lines, one of which includes the desired line, and for preparing the operating circuits for the clutch magnets individually included in the units of the selected group, means responsive to a second series of received impulses for selecting from the selected group of units the unit to which the calling line extends and for further preparing the operating circuit for the clutch magnet included in the selected unit, means operative following the operation of said last-mentioned means for completing the operating circuit of the clutch magnet included in said selected unit, means responsive to the operation of said last-men-

tioned means for completing the operating circuit to the one of said operating magnets which correspond to the odd or even number identifying the group of lines including the desired line, and 5 means responsive to a third series of received impulses for selecting the desired line from the selected subgroup of lines.

37. In a telephone system, a plurality of lines divided into odd and even numbered groups, and 10 line selecting means having access to said lines, said line selecting means comprising, in combination; a stepping switch including bank contacts arranged in sets and a wiper associated with each of said contact sets, a link line extending 15 to said stepping switch, a plurality of switching units each having a number of said lines terminating thereat and each including a control element movable in one direction to connect a subgroup of lines included in an odd numbered 20 group of lines to the bank contacts of said stepping switch and movable in another direction to connect a subgroup of lines included in an even numbered group of lines to the bank contacts of said stepping switch, each of said subgroups of 25 lines including two smaller subgroups of lines, a wiper switching relay for selectively associating said link line with the lines of one of two smaller subgroups of lines connected by way of one of said units to the bank contacts of said stepping 30 switch, means responsive to a series of received impulses for selecting a group of said units to which extend an odd numbered group of lines and an even numbered group of lines, one of which includes a desired line, and for determining, in accordance with the odd or even number identifying the group including said desired line, the 35 one of said operating magnets to be energized, means responsive to a second series of received impulses for further preparing the operating circuit for the one of said group of units to which the desired line extends and for determining the 40 condition of said wiper switching relay in accordance with the one of the two smaller subgroups of lines which includes the desired line, means operative following the operation of said last-mentioned means for completing the operating circuit for the clutch magnet embodied in the selected one of said units, means for completing the operating circuit of said one operating magnet, and means for operating said stepping switch in accordance with a third series of received 45 impulses, thereby to select said desired line and to associate it with said link line.

38. In a telephone system, a plurality of lines divided into odd and even numbered groups, and line selecting means having access to said lines, said line selecting means comprising, in combination; a stepping switch including bank contacts arranged in sets and a wiper associated with each of said contact sets, a link line extending to said stepping switch, a plurality of switching units each having a number of said lines 50 terminating thereat and each including a control element movable in one direction to connect a subgroup of said lines included in an odd numbered group of lines to the bank contacts of said stepping switch and movable in another direction to connect a subgroup of said lines included in an even numbered group of lines to the bank contacts of said stepping switch, each of said subgroups of lines including two smaller subgroups of lines, a wiper switching relay for selectively associating said link line with the lines of said 55 stepping switch, means responsive to a second series of received impulses for selecting a subgroup of lines from said selected group of lines, said subgroup being divided into two smaller subgroups one of which includes said desired line, means for connecting the lines of said selected subgroup to said bank contacts, and a wiper switching relay controlled by said second-mentioned impulse responsive means for associating said link line only with the wipers corresponding to the smaller subgroup of lines including the desired line.

39. In a telephone system, a plurality of lines including a subgroup of trunk lines, and connector means having access to said lines, said 60 connector means comprising, in combination; a plurality of switching units each having a number of said lines terminating thereat and at least one of said units having said trunk lines terminating thereat, said one unit including a control 65

40. In a telephone system, a plurality of lines including a subgroup of trunk lines, and connector means having access to said lines, said 70 connector means comprising, in combination; a plurality of switching units each having a number of said lines terminating thereat and at least one of said units having said trunk lines terminating thereat, said one unit including a control 75

one of two smaller subgroups of lines connected by way of one of said units to the bank contacts of said stepping switch, an operating member for actuating said elements, said elements normally being non-operatively associated with said member, means included in each of said units and comprising a clutch magnet for operatively associating the corresponding element with said member, operating circuits for said magnets, a first operating magnet for actuating said member to move any element operatively associated therewith in a direction to cause the associated unit to connect to the bank contacts of said stepping switch a subgroup of said lines included in an odd numbered group, a second operating 10 magnet for actuating said member to move any element operatively associated therewith in a direction to cause the associated unit to connect to the bank contacts of said stepping switch a subgroup of said lines included in an even numbered group, operating circuits for said first and second magnets, means responsive to a series of received impulses for preparing the operating circuits for the clutch magnets respectively included in the units of a group of said units to which 15 extend an odd numbered group of lines and an even numbered group of lines, one of which includes a desired line, and for determining, in accordance with the odd or even number identifying the group including said desired line, the 20 one of said operating magnets to be energized, means responsive to a second series of received impulses for further preparing the operating circuit for the one of said group of units to which the desired line extends and for determining the 25 condition of said wiper switching relay in accordance with the one of the two smaller subgroups of lines which includes the desired line, means operative following the operation of said last-mentioned means for completing the operating circuit for the clutch magnet embodied in the selected one of said units, means for completing the operating circuit of said one operating magnet, and means for operating said stepping switch in accordance with a third series of received 30 impulses, thereby to select said desired line and to associate it with said link line.

39. In a telephone system, a plurality of lines, and line selecting means having access to said lines, said line selecting means comprising, in combination; a stepping switch including bank contacts arranged in sets, and a wiper associated with each of said contact sets, a link line extending to said switch, means responsive to a series of received impulses for selecting a group of lines 50 including a desired line, means responsive to a second series of received impulses for selecting a subgroup of lines from said selected group of lines, said subgroup being divided into two smaller subgroups one of which includes said desired line, means for connecting the lines of said selected subgroup to said bank contacts, and a wiper switching relay controlled by said second-mentioned impulse responsive means for associating said link line only with the wipers corresponding to the smaller subgroup of lines including the desired line.

40. In a telephone system, a plurality of lines including a subgroup of trunk lines, and connector means having access to said lines, said 70 connector means comprising, in combination; a plurality of switching units each having a number of said lines terminating thereat and at least one of said units having said trunk lines terminating thereat, said one unit including a control 75

- element movable in one direction to select said subgroup of trunk lines and movable in another direction to select a second subgroup of lines, means responsive to a series of received impulses comprising a predetermined number of impulses for selecting a group of said units including said one unit and for selecting the direction of movement of said control element corresponding to said group of trunk lines, means responsive to a second series of received impulses comprising a predetermined number of impulses for selecting said one unit from said selected group of units, means operative following the operation of said last-mentioned means for moving said control element in said selected direction, thereby to select said trunk lines, and means operative following the operation of said last-mentioned means for selecting an idle one of said trunk lines.
41. In a telephone system, a plurality of lines including a subgroup of trunk lines, and connector means having access to said lines, said connector means comprising, in combination; a plurality of switching units each having a number of said lines terminating thereat and at least one of said units having said trunk lines terminating thereat, said one unit including a control element rotatable in one direction to select said subgroup of trunk lines and rotatable in the reverse direction to select a second subgroup of lines, means responsive to a series of received impulses comprising a predetermined number of impulses for selecting a group of said units including said one unit and for selecting the direction of rotation of said control element corresponding to said group of trunk lines, means responsive to a second series of received impulses comprising a predetermined number of impulses for selecting said one unit from said selected group of units, means operative following the operation of said last-mentioned means for rotating said control element in said selected direction, thereby to select said trunk lines, and means operative following the operation of said last-mentioned means for selecting an idle one of said trunk lines.
42. In a telephone system, a plurality of lines divided into odd and even numbered groups and including a subgroup of trunk lines, and connector means having access to said lines, said connector means comprising, in combination; a plurality of switching units each having a number of said lines terminating thereat and one of said units having said trunk lines terminating thereat, said one unit including a control element movable in one direction to select said subgroup of trunk lines and movable in another direction to select a second subgroup of lines, each of the remaining units including a control element movable in one direction to select a subgroup of lines

included in an odd numbered group of lines and movable in another direction to select a subgroup of lines included in an even numbered group of lines, means responsive to a series of received impulses for selecting a group of said units to which extend an odd numbered group of lines and an even numbered group of lines one of which includes a desired line and for determining the direction of movement of the control elements respectively embodied in the units of said selected group in accordance with the odd or even number identifying the one of said group of lines including the desired line, said last-mentioned means being responsive to a series of impulses comprising a predetermined number of impulses to select a group of said units including the unit to which said trunk lines extend and to select the direction of movement of the control element embodied in said last-mentioned unit which corresponds to said trunk lines, means responsive to a second series of received impulses for selecting the one of a selected group of units to which the desired line extends, said last-mentioned means being responsive to a series of impulses comprising a predetermined number of impulses to select the one of said units to which said trunk lines extends in the event the desired line is a trunk line, means operative following the operation of said last-mentioned means for moving the control element of the selected unit in the direction determined by said first-named means, thereby to select the subgroup of lines including the desired line, means operative in the event said desired line is a trunk line for automatically selecting an idle one of the selected subgroup of trunk lines, and means responsive to a third series of received impulses for selecting the desired line from the selected subgroup of lines in the event said desired line is not a trunk line.

43. In a signaling system, a plurality of lines, said lines being divided into odd and even numbered groups, switching apparatus having access to each of said lines, means responsive to a first series of received impulses for causing said switching apparatus to select simultaneously an odd numbered group and an even numbered group of said lines, means partially controlled in accordance with the odd or even number of impulses comprising said first series of received impulses and responsive to a second series of received impulses for causing said switching apparatus to select simultaneously one of said selected groups of lines and a subgroup of lines from said one selected group of lines, and means responsive to a third series of received impulses for causing said switching apparatus to select a line from said selected subgroup of lines.

JOHN E. OSTLINE.

CERTIFICATE OF CORRECTION.

Patent No. 2,171,669.

September 5, 1939.

JOHN E. OSTLINE.

It is hereby certified that error appears in the printed specification of the above numbered patent requiring correction as follows: Page 19, second column, line 72, claim 9, for the word "allotted" read allotter; and that the said Letters Patent should be read with this correction therein that the same may conform to the record of the case in the Patent Office.

Signed and sealed this 17th day of October, A. D. 1939.

Henry Van Arsdale,
Acting Commissioner of Patents.
